SUBMARINE MINE CONTROL SYSTEM

Alva F. Englehart, Fort Shafter, Hawaii, and Theodore Gunther, Fort Monroe, Va., assignors to the United States of America as represented by the Secretary of War

Filed May 24, 1939, Ser. No. 275,426

28 Claims. (Cl. 102—11)

(Granted under Title 35, U.S. Code (1952), sec. 266)

This invention relates to a system of submarine mine control, in which a group of mines submerged offshore and constituting a distant station is connected through a single conductor to a casemate or shore station, the respective mines of the group being remotely controlled from the casemate through the instrumentality of a normally inactive automatic selector situated at the distant station, whereby to permit the mines to be fired selectively from the casemate or automatically by impact.

One of the objects of this invention is to provide a submarine mine control system wherein the components of a mine field submerged offshore may be fired by impact through the action of a normally dormant automatic selector mechanism situated in the midst of the mine field at the distant station and functioning when a mine has been struck and armed by the impact to establish a path for the passage of electrical energy through the detonating elements of the mine from a source of high potential energy located at the casemate or shore station.

Another object of this invention is to provide a system of the type specified whereby the components of a submerged mine field may be selectively fired from the casemate or shore station through the conjoint action of an automatic selector situated at the distant station in the midst of the mine field and a series of interacting electro-mechanical devices controlled from the casemate and functioning when energized to cause the automatic selector to step to and lock on a selected mine for the purpose of establishing an electrical path for the passage of firing current through the detonating elements of the mine from a source of high potential energy at the casemate.

Another object of this invention is to provide a system of submarine mine control including a pair of automatic selectors, one of the selectors being located at the casemate or shore station, the other being disposed at the distant station in the midst of the submerged mine field, the two selectors, which are normally at rest on the home position, being adapted to step in coordinated sequence to, and to stop on a mine circuit which has been armed or grounded, the operating circuits for the respective automatic selectors embodying means for restoring the proper sequence to the selectors should their order of stepping relation be disrupted.

Another object of this invention is to provide a system of submarine mine control including a group of mines submerged offshore, an automatic selector situated in the midst of the mine group and coacting therewith to distribute electrical energy to the components of the group, a selector located at the casemate and adapted to step in coordinated relation with the offshore selector whereby the operator at the casemate or shore station may be informed at any time which mine in the group is operatively connected to the mine control assembly.

Another object of this invention is to provide a system of submarine mine control which when rendered alert by application of the operating power will be mechanically and electrically silent, that is to say, its operation will not involve the production of disturbances of either a mechanical or electrical nature which could be detected by detecting apparatus employed for the purpose of locating the mine field.

2

Another object of this invention is to provide a submarine mine control system embodying electro-mechanically controlled units which normally disrupt the firing circuit and preclude the application of firing power to the shore cable until the selector at the distant station has definitely locked on the mine selected for firing.

Another object of this invention is to provide a mine control system including interacting electro-mechanical means automatically controlled for removing all power from the shore cable and maintaining the system in this condition until the high potential energy circuits have been broken and the electro-mechanical components of the system restored to their normal positions, whereby to preclude accidental firing of the mine.

Other objects of this invention are to provide a submarine mine system wherein one or more mine groups may be controlled or supervised from a single supervisory assembly located at the casemate or shore station; to enable the electrical characteristics of the entire sys-

tem and of any mine circuit in the system to be readily ascertained at the shore station; to furnish a system which permits the nineteen mines of the submerged mine group to be successively fired while restricting application of the high potential firing power to each mine in the order in which the respective mines have been conditioned for firing and to afford a control system which utilizes an electronic discharge device to prevent the back flow of high voltage currents through the system to the generating plant.

With these and other objects in view this invention consists of certain details of construction, combination and arrangement of parts to be more particularly hereinafter described and claimed.

Briefly stated, this invention comprises a shore station or casemate consisting of a power unit (not shown) adapted to supply electrical energy for the system; a mine control assembly functioning to determine the flow of energy to the shore cable; a supervising assembly adapted to be connected with one or more mine control assemblies to enable supervision of the system and a distant station including a submerged mine field of nineteen mines and a distribution box situated in the midst of the mine field, the distribution box containing an automatic selector connected through the distribution box with the shore cable and with each of the nineteen mines, the selector functioning to establish an electrical path through each mine whereby it may be fired on impact or selectively fired from the casemate or shore station and for other purposes.

Referring more particularly to the accompanying drawings in which corresponding parts are indicated by similar reference characters:

FIG. 1 is a diagrammatic view partially in section and in elevation of casemate assembly A, a fragment of the connections extending between the source of electrical supply and the assembly, a portion of the connections between assembly A and assembly B and a part of the connection between assembly A and the distant station, and illustrating the components of assembly A in their normal positions;

FIG. 2 is a diagrammatic view partially in section and in elevation of casemate assembly B, a portion of the electrical connection extending between assembly A and assembly B, a fragment of the connections between the source of electrical supply and assembly B and a part of the shore cable between assembly A and the distant station and illustrating the components of assembly B in their normal position, with the wipers of the casemate selector serving its four levels on their home positions;

FIG. 3 is a fragmentary diagrammatic view partially in section and in elevation of distant station assembly C, a portion of the shore cable extending from assembly A,

and illustrating the components of assembly C in their normal position with the two wipers of the distant station selector on their home positions and the notch in the disk of said distant station selector overlying the remaining home position and showing in dotted outline the first step of the wipers after they have left their home positions;

FIG. 4 is a fragmentized diagrammatic view of the system partially in section and in elevation and illustrating in full lines the paths taken by the 110 volt operating current from its distributing terminal to the grounds at the casemate and at the distant station during the stepping operation of the casemate and distant station selectors and which are established immediately after the selectors have left their home positions, and said view showing in dotted outline those components of the system which are in their normal positions and which aid in forming certain of the paths for the 110 volt operating current to ground and further showing in full lines and in section, certain elements of the system which are in their operated positions and through which the current passes to ground;

FIG. 5 is a fragmentized diagrammatic view partially in section and in elevation of a fragment of the shore cable, the distributing assembly C at the distant station including the locking relay unit, the timing relay unit, the motor magnet, the distant station selector and a portion of the mine assembly E, and illustrating in full line the path of operating current from the shore cable to ground when the operating switch has been closed and the system is on the alert and showing in dotted outline the path taken by the 110 volt operating current immediately after a mine has been struck and the impact mechanism operated to move its ball to the position shown in dotted outline, certain of the components of the system through which the operating current flows and which are in their normal position being shown in dotted outline and certain elements through which the current passes but which are in operated position, being disclosed in full lines and in section;

FIG. 6 is a fragmentized diagrammatic view partially in elevation and in section and illustrating in full lines the path to ground taken by the 110 volt operating current and the 600 volt firing current when the distant station selector has locked on a grounded mine, certain of those components of the system which are in their normal positions, but through which the circuit passes, being shown in dotted outline and certain elements through which the current passes but which are in their operated position, being shown in full lines and in section;

FIG. 7 is a fragmentized diagrammatic view partially in section, partially in elevation, of the paths taken by the 110 volt operating circuit from its distributing terminal to ground when the coordinated stepping relation of the casemate and distant station selectors has been disrupted, the paths to ground taken by the operating current from its distributing terminal being shown in full line; the components of the system through which the current passes and which are in their normal positions, being shown in dotted outline, and those components through which the current passes but which are in operated position, being shown in full line and in section;

FIG. 8 is a fragmentized diagrammatic view partially in section and in elevation of the paths taken by the 110 volt operating current to ground when the distant stations selector has stopped on a grounded mine, said paths to ground being shown in full lines; the components of the system which are in their normal position but through which the current passes being shown in dotted outline and those through which the current passes, but which are in operated position, being shown in full lines and in section;

FIG. 9 is a side elevation of the distant station selector;

FIG. 10 is a top plan view of the distant station selector;

FIG. 11 is a fragmentized top plan view of the housing

75

for the distributing assembly at the distant station, with cover removed;

FIG. 12 is a transverse vertical section taken on the line 12—12 of FIG. 11;

FIG. 13 is a side elevation of the cover for the housing, shown in FIGURES 11 and 12, the fastening element for the cover being shown in position, and

FIG. 14 is a fragmentary detail of the distant station selector showing the relation of the wiper arms and notch in the selector disk.

The mine control systems heretofore designed have involved certain serious defects due to the use of alternating current as operating power for the system, a continuously rotating selector at the distant station, or circuit arrangements at the distant selector which under certain conditions rendered it possible for the high voltage firing current to reach the mine. The present invention overcomes these and other defects by using direct instead of alternating current as the power for operating the system, by substituting a normally inactive selector in place of a selector of the continuously rotating type and by isolating the fire mine circuit from the remaining mines. With these and other important provisions there is effected a system which to a large extent is detection proof and which affords a maximum degree of safety against premature mine explosions.

In the illustrated embodiment characterizing this invention and with special reference to FIGS. 1 and 2 of the drawings, there are shown mine control and supervisory assemblies A and B respectively, which in connection with the power unit, not shown, constitute the casemate or shore station. This station is adapted to be connected by a single conductor Y with the distant station, shown on FIG. 3, which consists of a distributing box assembly C and a mine field D. These three views when placed in end to end relation and collectively considered disclose the complete system which for the purpose of this discussion will hereinafter be considered under the headings and in the order to wit:

40 Casemate—Power Supply;
Casemate—Mine Control Assembly;
Casemate—Supervisory Assembly;
Distant Station—Distribution Box Assembly;
Distant Station—Mine Field;
Circuits and Their Function;
Conclusion.

CASEMATE—POWER SUPPLY

50 The requisite electrical energy for the system is furnished by a casemate power unit, not shown, having facilities for generating 110 volts direct current adapted to serve as operating power for the system, 45 volts alternating current for the signals in the supervisory assembly, 250 volts direct current for clearing the mines and locking the distant station selector on a selected mine, 110 volts alternating current adapted to heat the filament of the two-element electronic device in the mine control assembly and for operating certain audible and visible signals in the mine control and supervisory assemblies, and 600 volts rectified current for firing the mines. This power is rendered available at the distributing terminals of the casemate mine control and supervisory assemblies, as will hereinafter appear.

CASEMATE—MINE CONTROL ASSEMBLY

The 110 volt direct current, the 600 volt rectified current and the 110 volt alternating current referred to in the preceding paragraph, are conducted to terminals 1, 4, 5 and 6 of the group of terminals numbered 1 to 6 inclusive, attached to the back of the casemate panel; this power being applied to the system as follows: 110 volts direct current terminal 1, 600 volts rectified current terminal 4, 110 volts alternating current terminals 5 and 6. The remaining terminals 2 and 3 of the group are adapted

to be connected to the outgoing leads of signal circuits, which hereinafter will be referred to.

Mounted on the casemate panel is the mine control assembly A which for the purpose of this discussion will be broken down into the subordinate groups and units to wit: electronic valve group; signal group; power control group and relay group which includes the pilot relay unit; the control relay unit; the guard relay unit and the firing power relay unit.

The components of these groups and units, their electrical connections and their purpose will now be described. The electronic valve unit consists of a transformer 7 having primary and secondary windings 8 and 9, the primary winding 8 being connected with the 110 volt alternating current supply terminals 5 and 6, via conductors 10 and 11, and the secondary winding 9 being connected to the input and output leads 12 and 13 of the filament 15 of the two-element electronic valve 14, the plate 16 of which is connected to one end of conductor 17. This valve or diode 14 is included in the circuit of the operating power so as to prevent the back-flow of high potential energy to the power operating unit which would be possible should the switch of the control relay unit fail to release when firing power is flowing through the system.

The signal group is composed of four signal lamps, colored green, red, white and red and numbered respectively 18, 23, 28 and 38. The green signal 18 has its terminal 19 connected via conductor 21 to ground 21' and the remaining terminal 20 connected to one end of conductor 22. The red signal 23 has its terminal 24 connected to one end of conductor 26 branching from conductor 97, and the remaining terminal 25 connected to ground 25' via conductor 27. White signal 28 has its terminal 29 connected to the upper end of conductor 31 and the remaining terminal 30 connected to one end of conductor 32. Red signal 38 has its terminal 40 connected to one end of conductor 41 and the remaining terminal 39 connected to outlet terminal 2, via conductor 42. The white signal 28 when illuminated, indicates that the distant station selector is on the home position; the red signal that the distant station selector has locked on a mine circuit and that the system is in condition for the application of firing power. This signal also serves to indicate that the distant station selector has stopped on a grounded mine circuit and that the system is ready for the application of clearing power. The green and white signals glowing simultaneously indicate that a mine has been fired and that the distributing box fuse in the circuit of the fired mine has been blown. These two signals also indicate that all power has been removed from the shore cable and if clearing instead of firing power has been applied to the system, they likewise show that the fuse in the circuit of the fired mine has been blown. The red signal 38 serves to inform the casemate operator that the firing power switch at the power unit (not shown) has been closed and in consequence firing power is available at the casemate panel for the assembly A.

The power control group is composed of an operating switch 33, a firing switch 43, the two switches controlling respectively the application of operating and firing power to the system. A start key switch unit 56 provides a secondary control of the flow of operating power through the system and a clearing key switch unit 60 determines the flow of clearing power to the distant station. Operating switch 33 includes movable switch blades 33a and stationary contacts 34a, 34b, 34c and 34d, of which contact 34a is connected to the 110 volt direct current terminal 1 via conductors 45 and 74, contact 34b to the free end of conductor 32, extending from the white signal, contact 34c to the free end of conductor 17, extending from the plate 16 of the electronic valve 14, and contact 34d to ground 36 via conductor 35. When switch 33 is in closed position the plate circuit of the diode 14

is connected with the 110 volt direct current source of supply and one side of the white signal 28 is grounded.

The firing switch 43 includes movable switch blades 43a and the stationary contacts 44a, 44b, 44c, 44d, 44e and 44f, of which contact 44a is connected to one end of conductor 49 extending from conductor 50; contact 44b to distributing terminal 4 (the connection being made via conductor 51, to which the 600 volt rectified current is applied); contact 44c to outlet terminal 3 via conductor 52; contact 44d to one end of conductor 53 extending from the mid-point of secondary winding 9 of transformer 7; contact 44e to one end of the conductor 54 and contact 44f of distributing terminal 6, via conductors 55 and 11. When firing switch 43 is in closed position, 600 volts rectified current, constituting the firing power, is applied to the system, likewise a circuit through a green signal at the power unit (not shown) is completed to inform the operator at the power unit that firing power has been applied to the mine control assembly A. The switch 43 also closes a circuit to ground through one of the windings of the control relay unit, as will hereinafter appear.

Start key switch unit 56 comprises a pivotally mounted start key 56a and a switch set 56b including resilient finger-like contacts 1a and 2a of which contact 1a is adapted to be engaged by the tip of the key to separate said contacts when the key is operated in the direction of the arrow, thus disrupting the operating power circuit. Contact 1a of switch set 56b is connected to the free end of conductor 57 branching from conductor 53, while the remaining contact 2a is connected to conductor 59 via conductor 58.

The clearing key switch unit 60 includes a pivotally mounted clearing key 60a and a switch set 60b embodying stationary finger-like contacts 1b, 3b, 5b and movable interconnected contacts 2b-4b, adapted to be engaged by the clearing key 60a, so that when said key is actuated in the direction of the arrow the normally engaged contacts 4b-5b will be separated and the normally separated contacts 1b-2b and 3b-4b will be brought into engagement. Contact 1b of switch set 60b is connected to conductor 50 via conductor 63. Contact 2b to conductor 57 via conductor 64, contact 3b to one end of conductor 65, contact 4b to one end of conductor 66 and contact 5b to the free end of conductor 54, extending from contact 44e of the firing switch.

Clearing switch unit 60 when in its operated position functions to close the 110 volt operating circuit through one of the windings of the control relay unit, to complete the 250 volt clearing circuit through the distant station selector and to open the firing circuit.

As previously stated the relay group (FIG. 1) consists of the pilot, control, guard and firing power relay units. These will now be considered in the order of their enumeration. Pilot relay unit 67 embodies a winding 68, armature 69, and switch operating arm 70, which is interlinked with and controlled by the armature 69 to operate switch set 71 composed of a stack of contact members numbered 1c to 5c inclusive.

In this connection, it is to be understood the interlinked construction between the armature 69 and arm 70 is merely a diagrammatic showing to indicate control of the arm by the armature, since in actual practice this relay unit is of the telephone type as shown in the patent to Michael Setter, number 1,317,597, patented September 30, 1919, wherein a stack of contact members are mounted on the relay and operated by an armature-controlled mechanism as will be understood without further discussion.

When winding 68 of relay unit 67 is energized switch set 71 will be moved to operated position from the released position shown in the drawings. In other words the interconnected movable contact members 2c and 4c of the stack will be moved relative to the stationary members to separate contacts 1c and 2c and to close the normally separated members 2c-3c and 4c-5c.

To include contact members 1c to 5c of the stack in the

instant system, contact member 1c is connected via conductor 73 to conductor 31; contact member 2c to the 110 volt direct current distributing terminal 1 via conductor 74; contact member 3c to one end of conductor 75; contact member 4c to the 110 volt alternating current distributing terminal 6 via conductors 76 and 11, said conductor 76 being connected intermediate its ends to the branch conductor 41 extending from terminal 40 of red signal 38; contact 5c is connected to one end of conductor 77.

To include winding 68 of relay unit 67 in the system, one extremity of said winding is connected to conductor 84 and the other to conductor 83, for a purpose which will hereinafter appear. Pilot relay unit 67 when permanently energized operates the switch set 71 to disrupt the circuit of white signal 28, close that of red signal 23, open the circuit of the guard relay unit, close that of the firing power relay unit, complete the circuit of an alarm bell and a red signal in the supervising assembly B, hereinafter to be mentioned.

The control relay unit 78 comprises two winds 1a-2b, armature 79 and arm 80 which is interlinked with and controlled by the armature to operate switch set 81 as in the case of the pilot relay unit hereinbefore described. Switch set 81 is composed of a stack of contact members 1d to 6d inclusive, having contacts 2d-3d-5d interconnected for simultaneous movement by the armature controlled arm 80 so that energization of the windings 1a-2b of the relay unit moves the switch set from the released position, shown in the drawings (FIG. 1), to operated position which separates contacts 1d-2d and engages contacts 3d-4d and 5d-6d.

To tie the switch set 81 to the instant system contact member 1d is connected via conductor 83' to conductor 83; contact member 2d to the free end of conductor 50; contact member 3d to the free end of conductor 59; contact member 4d to the free end of conductor 22; contact member 5d to the free end of conductor 76 via conductor 85 and contact member 6d to conductor 77 via conductor 86.

To include the relay unit 78 in the system, winding 2b has one extremity connected to conductor 22 via conductor 82 and the other end connected to ground 88 through conductor 89 and balancing resistance 90, while the remaining winding 1a of the relay unit 78 has one extremity connected to conductor 91 and the other extremity to the free end of conductor 83, as clearly shown in FIG. 1 of the drawings.

The control relay unit 78 when operative functions to close the circuit through the green signal 18, remove all power from the short cable Y, complete the circuits of an audible and visible signal in the supervisory assembly B and disrupt the normal path of the 110 volt direct current through the pilot relay unit.

Guard relay unit 92 consists of winding 93, armature 94 and arm 95 which is interlinked with and controlled by the armature as in the case of the other relays previously described. As the guard relay 92 must be slow to release, its armature 94 is counterweighted as at 94a. Arm 95 is adapted to operate the switch set 95a consisting of the two contacts 1e-2e which are separated when the relay unit energizes.

To include the switch set 95a in the system contact 1e is connected to the free end of conductor 75 and contact 2e to one end of conductor 97. To include the winding 93 of the relay unit 92 in the system one end of said winding is connected through resistance 95b to conductor 31 while the other end of said winding is connected to ground 96 via conductor 96a. When in its operated position guard relay unit 93 serves to interrupt the circuit through the firing power relay unit 98 hereinafter to be mentioned.

The firing power relay unit 98 consists of winding 99, armature 100, armature arm 101, which is interconnected with and controlled by the armature to operate switch set

102 composed of the stack of contact members 1f to 4f inclusive, having contact members 1f-3f interconnected and adapted to be simultaneously moved by the armature arm 101 to engage contact members 1f-2f and 3f-4f. To associate the switch set 102 with the instant system, contact 1f is connected to the free end of conductor 91; contacts 2f and 3f are interconnected and contact 4f is connected to the free end of conductor 66. To connect the winding 99 of the relay unit 98 to the system, said winding has one end connected through resistance 103 to the lower end of conductor 97, and the other end to ground 104 via conductor 105, as clearly shown in FIG. 1 of the drawings. When in its operated position, relay unit 98 serves to complete the 600 volt firing power circuit and likewise the 250 volt clearing power circuit to the shore cable Y for a purpose hereinafter to be described.

In order to interconnect the mine control assembly A with the supervisory assembly B hereinafter to be referred to, the four leads 50, 59, 65 and 77, extending from the mine control assembly are connected to the terminals 50a, 59a, 65a and 77a of terminal block 106 (FIG. 1) and these terminals are in turn connected via conductors 50b, 59b, 65b and 77b to the distributing terminals 50c, 59c, 65c and 77c on the supervisory panel upon which there is mounted the supervising assembly B (FIG. 2) which will now be described.

Casemate or Shore Station Supervisory Assembly B

To furnish the supervising assembly B with the requisite power it is equipped with power terminals 110, 111, 112, 113 and 114, which are connected to the casemate power unit (not shown) and supplied with power as follows: terminal 110, 250 volts direct current; terminal 111, 110 volts direct current; terminals 112 and 113, 45 volts alternating current and terminal 114, 110 volts alternating current.

For the purpose of adequately supervising one or more mine control assemblies and their respective mine groups, there is provided a supervising assembly B, having the components to wit: alarm unit, jack group, start key controlled switch set, metering unit, test key controlled switch set, mine key group, mine signal group, relay group and automatic selector, which are conveniently arranged on a suitably dimensioned supervising panel at the casemate or shore station, as clearly shown in FIG. 2 of the drawings. These components, their electrical connections and functions will now be described in detail and in the order of their enumerations.

The alarm unit designated H, consists of a bell 115, a red signal 116, and a switch 117 and is included in the system as follows: terminal 118 of the bell is connected via conductors 119 and 120 to distributing terminal 77c and its other terminal 121 is connected to terminal 122 of the switch 117, the remaining terminal 123 of which is connected via conductors (124) and 125 to power terminal 114. The red signal 116 has one of its terminals connected to alarm terminal 77c, via conductor 120 and the other terminal to power terminal 114. Assuming switch 117 to be closed the bell 115 will be sounded and the red signal illuminated when the pilot relay unit and the control relay unit are separately or collectively operated. Opening the switch 117 disrupts the bell circuit. The red signal however, will continue to glow until the pilot relay unit or the control relay unit has been released.

The jack group includes a center jack I and a group jack J. Center jack embodies a series of stationary and movable contact members 1g to 8g inclusive, the movable contact members 1g-3g-4g-5g and 8g being shiftable relative to the remaining stationary contact members when a dummy plug 126 is inserted in the jack, as will be understood without further discussion. In the instant assembly but two of the contact members of the center jack are used, namely 7g and 8g and these are included in the system as follows: contact 7g is connected to one end of conductor 127 and contact 8g to the 45 volt ter-

terminal 113 via conductor 128. Center jack I functions as a seat for the dummy plug 126 and also serves to disrupt the 45 volt circuit of the mine signaling group.

Group jack J embodies a set of stationary and movable contact members designated 8h-7h-1h-2h-3h-4h-5h and 6h. Normally these contact members are disposed, as shown in FIG. 2 of the drawings, but when dummy plug 126 is removed from the center jack and inserted in the group jack the contact members 8h-7h, 1h-3h and 5h-6h will be separated and the contact members 1h-2h and 4h-6h brought into engagement for a purpose hereinafter to appear. To tie the group jack J to the instant system contact 8h is connected to terminal 59c via conductors 129, 130 and 131; contact member 7h to the 110 volt direct current terminal 111 via conductor 132; contact member 1h to the distributing terminal 59c via conductors 131', 130 and 131, contact member 2h to one end of conductor 133, the other end of said conductor being connected with conductor 134; contact member 3h to terminal 50c via conductor 135, resistance 136 and conductor 140; contact member 4h to one end of conductor 137; contact member 5h to terminal 59c via conductor 138', resistance 139, conductor 138 and conductor 131; contact member 6h to terminal 50c via conductors 139' and 140. The group jack J through certain of its contact members serves to normally establish a path for the operating current between the terminals 59c and 50c so as to permit the system to function without regard to the use of the supervisory assembly. When the dummy plug 126 is inserted in the group jack however, the movable contact members are shifted relative to the stationary members to interconnect the various components of the supervisory assembly with the mine control assembly, as will hereinafter appear.

The check key controlled switch set designated K is composed of a pivotally mounted key 142a movable to the right and left, as indicated by the arrows, to operate switch set 142b embodying movable and stationary contact members 1i to 9i inclusive, of which contact members 4i-7i-9i are interconnected for simultaneous movement. When key 142a is moved to the left contacts 4i-7i-9i will be actuated to separate the normally engaged contacts 3i-4i-6i-7i-8i-9i and to engage the normally separated contacts 4i-5i. When the check key is moved to the right the normally engaged contacts 1i-2i will be separated, as clearly shown in the drawings. To include the check key controlled switch K in the system contact member 1i is connected to conductor 137, via conductor 134, capacity 146' and resistance 147'; contact member 2i to one end of conductor 143; contact member 3i to one end of conductor 143'; contact member 4i to the free end of conductor 127; contact member 5i to one end of conductor 144; contact member 6i to one end of conductor 145; contact member 7i to one end of conductor 146; contact member 8i to one end of conductor 147; contact member 9i to one end of conductor 148. Check key controlled switch set K coacting with the automatic casemate selector to be hereinafter referred to, controls the 45 volt power circuits to the mine signal lights for signaling and checking purposes.

To inform the operator at the casemate with respect to the electrical status of the system, there is provided a metering unit composed of a milliammeter key L, a milliammeter MA and a volt meter V. Milliammeter key L consists of a series of contact members 1j to 8j inclusive, two of said members 3j-6j being interconnected to provide a shiftable element or key operable to the left or right to the positions designated "clear" and "operated" respectively on the drawings. To connect the metering unit to the instant system the contact members of the milliammeter key are connected as follows: contact member 1j to the 250 volt direct current terminal 110 via conductor 150; contact member 2j to conductor 151 via conductor 152; contact member 3j to the positive binding post 153 of milliammeter MA via conductor 154; contact

member 4j to one end of conductor 155; contact member 5j to one end of conductor 151; contact member 6j to one end of conductor 156; contact member 7j to conductor 155 via conductor 157, and contact member 8j to the free end of conductor 137. The remaining binding post 158 of the milliammeter MA is connected to conductor 156' via conductor 159. Voltmeter V has its positive binding post 160 connected to the conductor 154 via conductor 161 and the remaining binding post 161' connected to ground 162 via conductor 163. With the milliammeter unit connected as stated when the switch key element 149 is moved to the left to the position designated "clear," the milliammeter MA and voltmeter V will be included in the 250 volt direct current circuit employed for clearing purposes. Shifting the milliammeter key L to the right into the position designated "operated" includes the milliammeter and voltmeter in the 110 volt direct current operating circuit of the system, as will be understood without further discussion.

- 10 20 To enable adjustment of the ballast resistance until the total resistance of the shore cable is 200 ohms at which point the milliammeter MA should give a reading of 67 milliammeters, there is provided a test key controlled switch set designated M consisting of a pivotally mounted key 150a adapted to cooperate with a switch set 150b, comprising a series of stationary and movable contact members 1k to 8k inclusive, the contact members 2k-3k and 6k-8k being interconnected whereby movement of the key to the right opens the normally closed contacts 3k-4k, but closes the normally open contacts 1k-2k, while movement of the key to the left opens the normally closed contacts 5k-6k and 7k-8k, as clearly shown in the drawings.

When test key 150a has been moved to the right the 250 volt terminal, designated 110, will be connected with the test contact T on the casemate automatic selector and the circuit to ground 199 will be opened. Movement of the test key to the left disrupts the 250 volt circuit to the terminal 65c and opens the milliammeter shunt circuit. To include the test key controlled switch set in the instant system contact member 1k is connected to one end of conductor 165; contact member 2k to one end of conductor 166, the opposite end of said conductor being connected to conductor 167; contact member 3k is connected to one end of conductor 168; contact member 4k to one end of conductor 169; contact member 5k is connected to one end of conductor 169', said conductor 169' being connected through resistance 170 to milliammeter lead 154; contact member 6k is connected to the free end of conductor 156; contact member 7k to the 250 volt output terminal 65c via conductor 171; contact member 8k to the free end of conductor 151.

Mine Key Group

- 35 40 45 50 55 60 65 70 75 To apply locking power to a predetermined mine at the distant station, there is provided a mine key group composed of nineteen mine keys, one for each mine at the distant station and these keys are designated mk1 to mk19 inclusive. In the drawing but two of these keys mk1 and mk19 are shown, as this showing is deemed sufficient for the purpose of the instant disclosure. Each mine key includes four contact members designated 1m-2m-3m-4m. The contact members 2m-3m of each key are interconnected and adapted to be simultaneously moved relative to the remaining contact members of the set to break a normally established ground circuit to ground 199 or to close the 250 volt circuit to the corresponding contact of the automatic selector, as will hereinafter appear. The mine keys shown are connected with the system as follows: contact member 1m of mine key mk1 is connected to one end of conductor 172a; contact member 2m to conductor 150 via conductor 167, resistance 167a and conductor 167'; contact member 3m with one end of conductor 173 branching from conductor 196; contact member 4m with one end of conductor 174.

The contact members of mine key *mk19* are connected as follows: contact member *1m* to one end of conductor *172b*; contact member *2m* to conductor *166*, common to all the keys; contact member *3m* to the free end of conductor *174*, likewise common to all the keys; and contact member *4m* to the free end of conductor *169*. With the nineteen keys connected to the system in the manner stated, depression of a mine key establishes a 250 volt locking circuit through the correspondingly numbered mine at the distant station, as will hereinafter appear.

To inform the casemate operator with respect to the particular mine at the distant station upon which the system has locked, there is provided a group of suitably colored signal lights numbered *ms1* to *ms19* respectively, the circuits of which are controlled by the casemate selector stepping in coordinated sequence with the distant station selector. In the present instance but two of these lights, *ms1* and *ms19* are shown in connection with a white signal light *ms20* which indicates the home position of the respective selectors.

The signal lights shown are connected to the system as follows: one terminal of each of the signal lights *ms1* and *ms19* is connected to a common conductor *175* branching from conductor *147*. The remaining terminals of each of the lights are connected to conductors *176a* and *177n* extending from the contacts *c1* and *c19* of the casemate selector *CS*, hereinafter to be described. One terminal of the white light *ms20* is connected to conductor *179* extending from terminal *9i* of check key *K*. Conductor *179* is connected through branch conductor *179'* with the 45 volt alternating current terminal *112*. The remaining terminal of this light is connected via conductors *191* and *223* to the home contacts *H3* and *H4* of the automatic selector at the casemate, to be hereinafter referred to. With this arrangement it will be apparent as the casemate selector steps from contact *c1* to *c19* the nineteen signal lights will be successively illuminated and when the selector comes to rest on the home positions *H3* and *H4* the circuit through the white light *ms20* will be completed.

Relay Group

As previously stated, the relay group consists of an impulsive relay unit *P* and a synchronizing relay unit *Q*. The impulsive relay unit *P* is composed of windings *c* and *d*, armature *181* and arm *182*, which is interlinked with the armature and adapted to operate switch set *180*. This set consists of a stack of contact members *1n* to *6n* inclusive. The arm *182* coacts with the interconnected contact members *2n* and *4n* to move these members relative to the complementary members whereupon when winding *d* of the impulsive relay unit is energized, the switch set will be moved to operated position which opens the normally closed contacts *1n-2n* and *5n-6n* and closes the normally open contacts *2n-3n*-*4n-6n*, for a purpose to hereinafter appear.

To include the switch set *180* in the instant system, contact member *1n* is connected to one end of conductor *183*; contact member *2n* is connected to one end of conductor *184*; contact member *3n* is connected to one end of conductor *145* via conductor *185* and resistance *186*; contact member *4n* is connected to conductor *143* via conductor *187*; contact member *5n* to one end of conductor *188*; contact member *6n* to the upper end of winding *d*, the free end of said winding being connected to one end of conductor *189*. The remaining winding *c* of relay unit *P* has one terminal connected to conductor *143*, and its other terminal to conductor *145* through resistance *190*.

The functions of the impulsive relay unit *P* are (a) to momentarily disrupt the operating circuit through the motor magnet of the casemate or supervisory selector during the period that the distant station selector is stepping in order to maintain the coordinated sequence in

10

operation between casemate and distant station selectors; to hold the circuit through the casemate or supervisory selector in an open condition when a steady current of at least 50 milliamperes flows through the winding *d* of the impulsive unit. This condition will exist when the system has stopped on an armed mine (which normally draws 62 milliamperes), or on a mine circuit having a ground numerically less than 500 ohms; to establish a circuit to ground through the winding *c* to send the casemate selector to its home position and restore the normal operating sequence to the casemate and distant station selectors should they be out of step.

Synchronizing relay unit *Q* is composed of winding *192*, armature *193* and arm *194*, which is interlinked with and controlled by armature *193*, to operate switch set *195* consisting of a stack of contact members *1o* to *6o* respectively, the three contact members *2o-4o-5o* being interconnected for simultaneous movement by the arm *194* which moves the switch set to operated position when the winding *192* of the synchronizing unit has been energized. Movement of the switch set to operated position opens the normally closed contact members *1o-2o-3o* and *4o* and closes the normally open contacts *5o* and *6o*.

The switch set *195* is connected to the system as follows: contact member *1o* is connected to conductor *146*, via conductor *196*, capacity *196'*, resistance *197* and conductor *198*; said conductor *196* being also connected to the free end of conductor *173*, as clearly shown in the drawings (FIG. 2); contact member *2o* is connected to ground *199* via conductor *200*; contact member *3o* is connected to the free end of conductor *147*; contact member *4o* to the free end of conductor *148*; contact member *5o* to the lower end of winding *192* of the synchronizing relay unit, the opposite end of said winding being connected to the free end of conductor *189*; contact member *6o* is connected to conductor *201*. One end of conductor *201* is connected to the winding *192* adjacent its lower end, the remaining end of said conductor is connected through capacity *202* and resistance *203* to the lower end of winding *192*. Likewise the lower end of winding *192* is connected to the free end of conductor *155*, for a purpose which will hereinafter appear.

The purpose of the synchronizing relay unit *Q* is to disrupt the synchronizing circuit to ground during normal stepping of the selectors or when the system has stopped on a contacted or selected mine to prevent return of the casemate selector to its home position. It is also the purpose of this unit to break the mine signaling circuit during the operation of rechecking, as will hereinafter appear.

CASEMATE—SUPERVISORY ASSEMBLY

The automatic selector in assembly *B* is of the type shown and described in the treatise entitled "Automatic Telephone Practice," 3d edition by Harry E. Hershey, this selector, which for the purpose of the instant discussion, will be referred to as the casemate or supervisory selector *CS*, is adapted to step in coordinated sequence with the distant station selector, and briefly stated, it comprises a contact bank in the form of a half cylinder which is served by four wipers having their wiping ends arranged 180° apart so that when the wiping end of a wiper steps off the last contact in the row of contacts, the other wiping end of said wiper will engage the first contact in the row of contacts.

The contact bank is made up of four contact levels A—A, B—B, C—C and D—D, and designated respectively "Locking Level," "Synchronizing Level," "Signal Level Direct," "Signal Level Check." The wiper set of the selector is composed of wipers *204*, *205*, *206* and *207*, which are suitably mounted in insulated relation on a common shaft *207'*. Shaft *207'* is adapted to be rotated in the direction of the arrows by a step-by-step mechanism including a motor magnet *MM*, comprising winding *208*, armature *209* and armature arm *210*, the latter being interconnected with the armature *209* and having a stepping pawl (not shown) adapted to coact with a ratchet

70
75

(not shown) mounted on shaft 207' so that the return movement of the arm 210 after its retraction, will impart a step-by-step rotary movement to the four wipers of the selector.

When winding 208 of motor magnet MM energizes, arm 210 will be retracted and when said winding 208 is deenergized the arm will be restored to its original position under spring action. This retraction of the arm and subsequent return to its initial position functions to simultaneously advance the wipers 204, 205, 206 and 207 in a step-by-step fashion, as will be understood without further discussion. As the arm 210 retracts it separates the make-and-break contacts 211 and 212 and as said arm is restored by spring action to its normal position, as shown in FIG. 2 of the drawings, said contacts 211 and 212 are returned to their normally engaged relation.

To include the automatic selector in the system, the upper end of its motor magnet winding 208 is connected to one end of branch conductor 213 extending from conductor 143. The opposite end of winding 208 is connected to conductor 188. Make-and-break contact 211 on the motor magnet MM is connected to one end of conductor 214, the other end of said conductor being attached to a conductor 215, which through resistance 216 and capacity 217 is connected to the remaining make-and-break contact 212, likewise connected to the free end of conductor 184.

In regard to the contact bank of the automatic selector, the level A—A and designated "Locking Level" is adapted to have its contacts *a1—a19* connected to the free ends of the nineteen conductors adapted to extend from the nineteen mine keys *mk1* to *mk19* inclusive. In the instant disclosure but two of these conductors are shown, namely *172a—172b* extending from the mine keys *mk1* and *mk19* and these are connected to the contacts on level A—A numbered *a1—a19* respectively. Level A—A is also provided with a testing contact T and a home contact H1, the testing contact T being connected with the free end of conductor 165 extending from contact *1k* of test key M, for a purpose hereinafter to appear.

The contact level B—B designated "Synchronizing Level" has its contacts *b1—b23* interconnected and attached to the free end of conductor 220 extending from conductor 168. One of the remaining contacts *b24* is connected to the free end of conductor 168 via conductor 221 and breaking resistance 222. The other of the remaining contacts *b24* is adapted to function as the home position designated H2 for the wiper 205.

The contacts *c1* to *c19* of the level C—C designated "Signal Level Direct" are adapted to be connected to the nineteen conductors extending from the mine signal lights designated *ms1—ms19*. In the present instance but two of the contacts *c1* and *c19* are shown connected, contact *c1* being connected to one side of light *ms1* via conductors 176b and 176a and contact *c19* to one side of light *ms19* via conductor 177n. The home contact H3 of level C—C is connected to the home contact H4 of level D—D via conductor 223. Conductor 223 is in turn connected to the free end of conductor 191 extending from one side of the signal light *ms20* indicating the home position of the selector wipers. The remaining side of the signal lights *ms1—ms19* is connected to conductor 175 branching from conductor 147. The remaining side of signal light *ms20* is connected via conductor 179 with contact *9i* of check switch K.

Contacts *d1* to *d19* of the level D—D designated "Signal Level Check" are adapted to be connected to nineteen conductors extending from one side of the mine signaling lights *ms1—ms19* inclusive. But two of these conductors are shown in the present instance, namely 176a and 177n, conductor 176a being connected to contact *d1* and conductor 177n to contact *d19* via branch conductor 225. In this connection it is to be noted that contacts of level D—D advance numerically from *d1* to *d19* in an anti-clockwise direction, while in the signal lev-

el C—C the numbers of the contacts advance numerically in a clockwise direction. With this arrangement it is possible to use the mine signal lights for checking purposes, as will hereinafter appear.

In order to connect the wipers of the automatic selector to the instant system, wiper 204 is connected to the free end of conductor 143; wiper 205 to the free end of conductor 146; wiper 206 to the free end of conductor 143' and wiper 207 to the free end of conductor 144, as clearly shown in FIG. 2 of the drawings.

Having outlined the arrangement and electrical connections of the components of the casemate assembly B, attention will now be directed to the distant station.

DISTANT STATION

15 The distant station includes a distributing box assembly C, and a mine field D, composed of nineteen mines, the respective mines and the distributing assembly C being in electrical relation with the mine control assembly over a single conductor or shore cable Y extending from the variable ballast resistance Z in assembly A to the distributing box assembly at the distant station, as clearly shown in FIG. 3 of the drawings.

16 Distributing box assembly C for the purpose of this description will be considered in the order of its principal groups and units to wit: distributing box or casing DB; locking relay unit LR; timing relay unit TR and automatic distant station selector DS. These units will now be discussed in the order of their enumeration and with particular reference to FIG. 3 of the drawings.

20 *Distributing box.*—The distributing box DB which is adapted to be positioned in the midst of the mine field D consists of a suitably dimensioned annular casting having a base 230 and a cylindrical wall 231, formed with a circular flange 232. This flange is provided with a shore cable inlet 233 and nineteen mine cable outlets 234 for the passage of the nineteen conductors *p1* to *p18* inclusive, extending to the nineteen mines of the field D. Bushings 236 which are disposed in the inlet and outlet openings 233 and 234 respectively are adapted to surround the conductors and prevent the ingress of water as will be readily understood without further discussion.

25 A cover 237 is adapted to be bolted to flange 232 against the compressible gasket 238. A mounting or frame 239 is positioned within the casting and functions to support the distributing assembly. Frame 239 is enclosed by a cap member 240 having apertures in its top portion for the passage of the tips of fuses 241 (FIG. 13), and in this connection it might be noted that one of the fuses 241 is adapted to be included in each of the mine circuits.

30 *Locking relay unit.*—Locking relay unit LR consists of a relay 242 including winding 243, armature 244 and arm 245 interlinked with and operated by the armature to move the switch set 246 to operated position. Switch set 246 includes a stack of contacts *1p* to *7p* inclusive of which contacts *2p* and *5p* are interconnected. In the normal or released position of the switch, contacts *1p—2p*, *3p—4p* and *6p—7p* are closed. Actuation of the switch set to its operated position opens the previously mentioned closed contacts and closes contacts *2p—4p* and *5p—7p*, for a purpose to hereinafter appear. The contacts of the switch set 246 are connected to the system as follows: contact *1p* to one end of conductor 252, contact *2p* to distributing terminal 253 to which the shore cable Y is

35 also attached; contact *3p* to ground 254, via conductor 255 and leakage resistance 256; contact *4p* to resistance 248' via conductor 249'; contact *5p* to ground 257 via conductor 258 and leakage resistance 259; contact *6p* to one end of conductor 260 and contact *7p* to the upper end of conductor 261. To include relay 242 in the system, the upper end of its winding 243 is connected to the distributing terminal 253 via conductor 248, resistance 248' and conductor 247. The remaining end of winding 243 is connected to ground 249 via conductor 250 and leakage resistance 251.

Timing relay unit.—The timing relay unit TR consists of a relay 262, including windings 262a and 262b, armature 263 and switch operating arm 264 interlinked with and operated by the armature to move switch set 265 to operated position. Switch set 265 includes a stack of contacts 1q-2q-3q and 4q, of which contacts 2q and 4q are interconnected for simultaneous movement. These contacts are tied into the system as follows: contact 1q to ground 266 via conductor 267; contact 2q to one end of conductor 268'; contact 3q to conductor 252 via branch conductor 269; contact 4q to one end of conductor 270. To include the winding 262a of relay 262 in the system, one end of said winding 262a is connected to the free end of conductor 260 and the opposite end to junction terminal 271 via conductor 272, resistance 273 and conductor 274. Winding 262b has its upper end connected to junction terminal 271 via conductor 275 and resistance 276. The opposite end of winding 262b is connected to ground 266.

Distant station selector.—The construction of the automatic selector DS in the distributing assembly C is substantially the same as that of the selector used in the casemate assembly B with exception of the wiper arrangement which in the case of the distant selector DS is modified so as to replace two of the four wipers used in the casemate selector with a peripherally notched disk which is adapted to engage the lower row of contacts in the contact bank for a purpose to hereinafter appear. Reference being had to FIGS. 3, 9, 10 and 14, of the drawings, the distant station selector DS comprises a motor magnet MN having a winding 279. The armature 279a of magnet MN is interlinked with and controls the movement of armature arm 280 and its depending stepping pawl 281. Energization of magnet MN moves the arm 280 to the left (FIG. 10), and in so doing closes the normally open contacts 1r and 2r mounted upon the motor magnet. When magnet MN is deenergized, spring 282 returns arm 280 to its original or normal open position, as shown in FIGS. 3 and 10 of the drawings.

The preceding structure is positioned upon a suitable base plate 283 adjustably associated with frame 284 of the contact bank CB, which is composed of three semi-circular rows of contacts a—a, b—b and c—c. For the purpose of this description the arcuate rows a—a, b—b and c—c will be designated "Upper Mine Level," "Middle Mine Level" and "Fan Level" respectively. The bank of contacts CB is adapted to be served by two wipers 285 and 286 and a disk 287, which rotates with the wipers and coacts with the contacts of fan level c—c, as shown in FIG. 3 of the drawings.

Wipers 285 and 286 and disk 287 are mounted in insulated relation upon and keyed to a shaft 288 suitably journalled in the parallel sides of base 283. Shaft 288 is provided with a ratchet 289 adapted to be engaged by the pawl 281 for the purpose of causing a step-by-step rotary movement of the shaft and imparting a similar movement to the wipers 285, 286 and disk 287, keyed to the shaft, the movement of the two wipers as viewed from the right being anti-clockwise and that of the disk as viewed from the opposite direction being clockwise, as indicated by the arrows FIG. 3.

Disk 287 serving fan level c—c is peripherally formed with diametrically opposed notches 290 which are adapted to underlie the contact-wiping-ends of the respective wipers 285 and 286 and to follow these wiping ends as they successively engage the contacts of their respective levels. Hence as the contact wiping ends of wipers 285 and 286 in the course of their step-by-step movement engage the contacts of levels a—a and b—b, one of the notches 290 will uncover the contact in the fan level c—c which is in electrical connection with the contact in level a—a or b—b engaged by the wiping end of wipers 285 or 286 (FIG. 14). With this arrangement it will be seen that with exception of the contact uncovered by the notch the contacts of fan level c—c are always in engagement

with the disk as it rotates. In other words one of the notches 290 will successively exclude one of the contacts of fan level c—c from the normal association of the contacts and the disk as the latter is rotated step-by-step with the two wipers.

The twelve contacts in mine level a—a include ten effective contacts designated m2, m4, m6 to m18 and h, the designations m2 to m18 representing the mine connected contacts and the character h the home contact.

10 The fourteen contacts of mine level b—b include twelve effective contacts, ten being designated m1, m3, m5 to m19 and two t and h1, the contacts m1 to m19 representing the mine connected contacts, the contact t a testing contact and the contact h1 a home contact. The twenty-five contacts of the fan level c—c include twenty active contacts designated s1 to s19 inclusive, representing the mine connected contacts and a home contact respectively. In this regard it is to be noted that the spacing of the contacts in levels a—a and b—b is such, when the wiping end of wiper 286 is in engagement with contact m1, the wiping end of wiper 285 is between the inactive contact and contact m2 of level a—a, and when the wiping end of wiper 286 is between the contacts m1 and m3 of level b—b the wiping end of wiper 285 is on contact m2 of level a—a and so on to the nineteen contacts.

20 The various contacts of the three levels a—a, b—b and c—c are electrically interconnected as follows: contact m1, level b—b to contact s1 level c—c, via conductor n1; contact m2, level a—a to contact s2, level c—c via conductor n2; contact m3, level b—b to contact s3 level c—c via conductor n3; contact m4, level a—a to contact s4, level c—c via conductor n4; contact m5, level b—b to contact s5, level c—c via conductor n5; contact m6 and so on to the contact m19, level b—b which is connected to contact s19, level c—c via conductor n19.

30 In level a—a the home contact h is connected to the free end of conductor 261 extending from contact 7p of locking relay LR (FIG. 3). In level b—b the home contact h1 is connected to the free end of conductor 270 and the testing contact t to ground 292 via conductor 293, resistance 294 and conductor 295. In level c—c the home contact h2 is connected to ground 296 via conductor 297, as clearly shown in FIG. 3 of the drawings. The nineteen conductors n1 to n19 interconnecting the three levels a—a, b—b and c—c of the contact bank are adapted to be connected via conductors o1 to o19 inclusive, with the lower ends of the nineteen mine fuses 241, the upper ends of these fuses being connected 40 with the nineteen mines M1 to M19 via conductors p1 to p19.

45 In this connection, it is to be noted in passing, that it is one of the fuses 241 which is adapted to be blown by the clearing power, for the purpose of releasing the distant station selector so that it will step to the home position. Usually fuse 241 is blown with the mine, sometimes, however, this does not occur and in this event the fuse must be blown before the selector will release.

50 To electrically connect the distant station selector DS with the system its two wipers 285 and 286 which are interconnected by conductor 298 are connected to conductor 291 extending from conductor 250 (FIG. 3), while the disk 287 is connected to junction 271 via conductor 300.

60 Having outlined the various components of the distributing box assembly their construction and electrical connections, attention will now be directed to the mine field D.

DISTANT STATION—MINE FIELD

65 Each of the nineteen mines forming the mine field D includes a mine assembly E consisting of a circuit-closing relay unit CR, an impact-operated mine-arming mechanism IM adapted to coact with the relay unit CR, a resistance element in the form of a neon tube and firing

relay unit FR adapted to control suitable detonators. These components will now be considered in the order of their enumeration.

Circuit-closing relay unit CR is composed of a relay 301 including winding 302, armature 303 and armature arm 304, which is interlinked with and controlled by the movement of the armature 303. The armature arm 304 is adapted to operate switch set 305 embodying a stack of contacts 1s, 2s and 3s, as shown in FIG. 3 of the drawings. To include switch set 305 in the instant system, contact 1s is connected to ground 306, via conductor 307; contact 2s to winding 302 at a point substantially midway of its length, via conductor 308; contact 3s to one side of the neon tube 309 via conductor 310. To electrically tie the winding 302 of the relay 301 into the instant system, the armature end of said winding is connected to mine tunnel 311 via conductor 312. Terminal 311 in each of the mine assemblies E, is adapted to be connected to one of the nineteen conductors p1 to p19, extending from the distant station selector. In the illustrated embodiment terminal 311 is connected to conductor p19 which through fuse 241 and conductors o19-n19 is connected to contact m19, level b—b of the automatic selector. The remaining end of winding 302 is connected to the winding of the firing relay via conductor 312', resistance 313 and conductor 314, as shown in FIG. 3 of the drawings.

Coating with switch set 305 is an impact mine arming mechanism comprising inclined surfaces 315 and 316 and a ball 317 upon which there normally rests a member 318 depending from contact 1s of switch set 305. This arrangement holds the contacts 1s-2s in spaced relation and maintains the normal unarmed condition of the mine, as shown in FIG. 3 of the drawings. When a mine has been struck, the impact rolls the ball along one of the inclined surfaces 315 or 316 and permits the lower end of member 318 to descend to the rear of the ball. This displacement of the ball and consequent drop movement of contact 1s, closes contacts 1s-2s and thus arms the mine. The armed status of the mine will continue until the circuit-closing relay 301 has been energized. When this occurs armature 303 will elevate armature arm 304 to engage contact 3s with depending contact element 304' of contact 1s. As the upward movement of the arm 304 continues it opens contacts 1s-2s and lifts member 318 from the path of the ball sufficiently to permit the latter to assume its original position. The mine is now in condition for the application of firing power. Deenergization of relay 301, restores arm 304 to its original position and leaves the lower end of member 318 resting on top of the ball, with all contacts open. The mine impact mechanism and the contacts 1s, 2s and 3s are now in their normal position.

The resistance element in the form of a neon tube 309 is employed to provide a bypass to ground 306 for a current, the potential of which is sufficient to break down the resistance of the neon tube, as previously stated. One side of neon tube 309 is connected to contact 3s of switch set 305 via conductor 310 and the other side to ground 306 via conductors 319 and 307.

The firing relay unit FR is composed of a relay 320 and a switch set 321. Relay 320 comprises winding 321', armature 322 and armature arm 323 which is connected with the armature 322 and is adapted to operate switch set 321 embodying a stack of contacts 1t to 4t inclusive, two of which 2t and 4t are interconnected for simultaneous movement. To include the switch set 321 in the system contact 1t is connected to the armature end of relay winding 302 via conductor 325; contact 2t to one of the binding posts 326 of detonator 327 via conductor 328, the remaining binding post 329 of detonator 327 is connected to one end of conductor 330; contact 3t is connected to binding post 331 of detonator 332 via conductor 333, which is also connected to the free end of

conductor 330. The remaining binding post 334 of detonator 332 is connected to conductor 328 via conductor 335. Contact 4t is connected to the lower end of winding 321' via conductor 336.

To include the winding 321' of firing relay FR in the system, the upper end of said winding is connected to contact 3s of switch set 305 via conductor 337 and the opposite end of said winding is connected as previously stated to winding 302 via conductor 314, resistance 313 and conductor 312'. When the firing relay energizes, armature arm 323 moves switch set 321 to operated position and in so doing closes the circuits including one of the detonators 327 and 332 to fire the mine.

The components of the several mine assemblies having been described, this discussion will be directed to the principal circuits of the instant system: Normal Operating Circuit; Stepping Circuit; Firing Circuit—Impact, Observation or Locking Circuit; Firing Circuit—Casemate Selected; Clearing Circuit; Selector Synchronizing Circuits; Testing, Checking and Mine Signal Circuits.

CIRCUITS AND THEIR FUNCTION

Normal operating circuit.—Assuming the casemate power unit (not shown) to be delivering the requisite power to the distributing terminals of the casemate assemblies A and B, the firing switch 43 to be closed, the dummy plug 126 to be in group jack J (to connect the mine control assembly A to the supervisory assembly B), and that the components of the system are otherwise as shown on FIGS. 1, 2 and 3 of the drawings; with this assumption, when operating switch 33 of mine control assembly A (FIG. 1), has been closed, a circuit will be established from the 110 volt direct current power distributing terminal 1 of the mine control assembly A, to the junction terminal 253 of distributing assembly C (FIG. 3), through diode 14, secondary winding 9 of transformer 7, winding 208 of motor magnet MM, a portion of winding 192 of synchronizing relay unit Q, cable Y extending between the casemate and distant stations) to junction 253.

This circuit may be traced as follows: (FIGS. 1, 2, 3 and 4) power terminal 1, conductor 45, terminal 34a of operating switch 33, terminal 34c of said switch, conductor 17, anode and cathode 16 and 15 of diode 14, secondary winding 9 of transformer 7, conductors 53 and 57, contacts 1a, 2a of start switch 56, conductors 58 and 59, terminal 59a of terminal block 106, conductor 59b (FIG. 2, terminal 59c, conductors 131, 130 and 131', contacts 1h-2h (closed by insertion of dummy plug), conductors 133, 134, contacts 1i, 2i, check key K, conductors 143 and 213, winding 208 of motor magnet MM, conductors 215 and 214, contacts 211 and 212 of the motor magnet MM, conductor 184, contacts 2n-1n of the switch set 180 of impulse relay unit P, conductor 183, a portion of winding 192 of synchronizing relay unit Q, conductors 155 and 157, contacts 7j-8j of milliammeter key L, conductor 137, contacts 4h-6h of group jack J, conductors 139' and 140, terminal 50c, conductor 50b, terminal 50a of terminal block 106 (FIG. 1, conductor 50, contacts 2d-1d of control relay unit 78, conductors 83' and 83, winding 68 of pilot relay unit 67, conductor 84, ballast resistance Z and shore cable Y to junction 253. From the junction terminal 253 (FIG. 3), there are two paths which may be taken by the current to the ground 266. One of these paths is as follows: junction terminal 253, contacts 2p-1p of the switch set 246 of locking relay unit LR, conductor 252, winding 279 of motor magnet MM, conductor 268' contacts 2q-1q of switch set 265, of timing relay unit TR, conductor 267 to ground 266.

The other of the paths to ground 266 is as follows: junction terminal 253, conductor 247, resistance 248', conductor 248, winding 243 of locking relay unit LR, conductors 250 and 291, wiper 285 of distant station selector DS, home contact h, conductor 261, contacts 7p-6p of switch set 246 of locking relay unit LR, conductor 260, winding 262a of timing relay unit TR, conductor 272, resistance 273, conductor 274, junction 271, resist-

ance 276, conductor 275, winding 262b of timing relay unit TR to ground 266.

Closing operating switch 33 of the mine control assembly A, likewise completes a circuit from power terminal 1, through white light 28 to ground 36 as follows: power terminal 1, conductor 74, contacts 2c-1c, pilot relay unit 67, conductors 73 and 31, terminals 29 and 30 of the white signal lamp 28, conductor 32, contact 34b, operating switch 33, contact 34d, conductor 35 to ground 36. When power was applied to the terminal 1, its application established a circuit through guard relay unit 92 to ground 96 FIG. 1, as follows: power terminal 1, conductor 74, contacts 2c-1c of switch set 71 of pilot relay unit 67, conductors 73 and 31, resistance 95b, winding 93 of guard relay unit 92, conductor 96a to ground 96. This circuit energized guard relay unit 92 and through its armature arm 95 moved switch set 95a to operated position, which opens contacts 1e-2e and disrupts the high potential firing power circuit from power terminal 4 to which 600 volts rectified alternating current has been applied. The system is now on the alert, that is to say, white light 28 is glowing at the casemate indicating that the distant station selector is on the home position; switch set 95a of guard relay unit 92 is in its operated position breaking the 600 volt firing circuit and switch set 265 of the timing relay unit TR FIG. 3, is likewise in operated position disrupting the circuit to motor magnet MN of the distant selector, as clearly shown in FIG. 5 of the drawings. Otherwise the components of the system are as shown on FIG. 1, 2 and 3 of the drawings.

Stepping circuit.—With the system on the alert and ready for action, let it be assumed that an enemy vessel attempting to navigate the mine field D strikes one of its mines, for instance mine number 19. The impact of the vessel tilts the mine and causes ball 317 of the impact mechanism IM in mine assembly E (FIGS. 3 and 5), to descend one of the inclined surfaces 315 and 316. Displacement of ball 317 enables member 318 FIG. 5, to drop behind it, permitting contact 1s of switch set 305 of circuit closing relay unit CR to assume the dotted line position shown on FIG. 5 of the drawings, thus closing contacts 1s-2s of switch set 305 of the circuit-closing relay unit CR and establishing the ground 306. Since 110 volts of direct current are available at junction 253, FIGS. 3 and 5, when the ground 306 has been established, a circuit will be formed through winding 243 of locking relay unit LR, which is in its normal or unretracted position, wiper 285 of the distant station selector DS, winding 262a of timing relay unit TR, disk 287 of the distant station selector to ground 306 as follows: FIGS. 3 and 5, terminal 253, conductor 247, resistance 248', conductor 248, winding 243 of locking relay unit LR, conductor 250, wiper 285, home contact h, conductor 261, contacts 7p-6p of switch set 246, conductor 260, winding 262a of timing relay unit TR, resistance 273, conductor 274, junction 271, conductor 300, disk 287, contact s19, engaged by the disk 287 FIG. 5, conductors n19-o19, fuse 241, conductor p19, a portion of winding 302 of the circuit-closing relay unit CR, conductor 308, contacts 2s-1s of switch set 305, of circuit-closing relay unit CR, conductor 307 to ground 306.

Completion of the stepping circuit by mine impact causes the locking relay unit LR to function and to move its switch set 246 to operative position which opens contacts 1p-2p, 3p-4p, 6p-7p and closes contacts 2p-4p, 5p-7p. Opening contacts 1p-2p, 3p-4p, 6p-7p breaks the 110 volt supply circuit between junction 253 and conductor 252; cuts out the leakage path to ground 254 through resistance 256 and breaks the circuit through winding 262a of the timing relay unit TR which permits switch set 265 of said timing relay unit to return to its normal or unretracted position, as shown in FIG. 3 of the drawings. Closing contacts 2p-4p, 5p-7p provides leakage paths to ground 249 through resistance 251 and introduces the resistance 259 to ground 257 for a pur-

pose hereinafter to be stated. With switch set 246 of locking relay unit LR in its retracted position and switch set 265 of timing relay unit TR in its normal or unretracted position the ground 306 established by mine impact, as previously stated, is momentarily cut out [contacts 6p-7p being open] and replaced by ground 257 in the circuit as follows: junction 253, conductor 247, resistance 248', conductor 248, winding 243 of locking relay unit LR, conductors 250-291, wiper 285, home position h of the distant station selector, conductor 261, contacts 7p-5p, resistance 259, ground 257. The formation of this circuit from junction 253 to ground 257 substitutes resistance 259 for resistance 273 and replaces the leakage path to ground 254 through resistance 256 with the leakage path to ground 249 via resistance 251. This change in the electrical characteristics of the circuit from junction 253 to ground 257 reduces the value of the current flow through the circuit below the holding requirements of locking relay unit LR which causes said locking relay unit to release its switch set 246. When the latter has returned to its normal position, contacts 2p-1p, 6p-7p will be closed to establish a flow of current from junction 253 to ground 266 through winding 279 of the motor magnet MN and contacts 1q-2q of the switch set 265 of timing relay unit TR which energizes motor magnet MN, thereby causing the wiper 285 to leave its home position h for a purpose hereinafter to be stated. In this connection, it is to be noted that, when switch set 246 of the locking relay unit LR returns to its normal or unretracted position and before the wiper 285 of the distant station selector has left its home position h, ground 306 will have been re-established. As this circuit from junction 253 to ground 306 includes but one coil 260a of the timing relay unit TR, the switch set 265 of the latter (which is in its normal or unretracted position) will not be affected to disrupt the circuit through winding 279 of motor magnet MN. When motor magnet MN has been energized, its armature controlled arm 280 functions to close the motor magnet contacts 1r-2r and to establish a circuit to ground 266 through winding 262b of the timing relay unit TR as follows: FIGS. 4 and 5, junction 253, contact 2p-1p of switch set 246, conductor 252, contacts 1r-2r, conductors 275' and 275, winding 262b of timing relay unit TR to ground 266.

This circuit causes the timing relay unit TR to function and to move its switch set 265 to operated position which opens contacts 1q-2q and breaks the circuit to ground 266 through the winding 279 of motor magnet MN. Motor magnet MN having been deenergized, its retractile spring FIGS. 9 and 10, retracts armature arm 280 and in so doing rotates the shaft 288 sufficiently to impart the starting step to the wipers 285 and 286 and disk 287 of the selector. As the wiper 285 leaves its home contact h, the circuit from junction terminal 253 to ground 306 in mine assembly E, including winding 243 of locking relay unit LR, winding 262a of timing relay unit TR, and disk 287 is broken permitting return of the switch sets 246 and 265 to their normal positions. Meanwhile wiper 286 has engaged mine contact m1 and disk 287 stepping with the two wipers, has advanced its notch 290 one step to effect engagement of said disk and home contact h2 forming a circuit from junction 253 to ground 296, FIGS. 4 and 5, as follows: junction 253, conductor 247, resistance 248', winding 243 of locking relay unit LR, conductors 250 and 291, conductor 298, mine contact m1, conductor n1, mine contact s1, disk 287, home contact h2, conductor 297 to ground 296. Throughout the period that the circuit just described from junction 253 to ground 266 through disk 287 remains effective, switch set 246 of locking relay unit LR retains its normal or unretracted position while switch set 265 is alternately retracted and released to cause the operation of the stepping magnet MN. In this connection it is to be understood that the complete circuit from power terminal 1

to junction terminal 253 remains the same as originally traced, as shown in FIG. 4 of the drawings.

When the preceding circuit from junction 253 to ground 296 via disk 287 has been established, a steady ground will be provided for the stepping operation of the selector in the supervisory assembly B at the casemate or shore station, so that the latter will function in proper coordinative sequence with respect to the distant station selector DS which is stepping by virtue of the circuit established from junction 253, contacts 2p-1p of switch set 246 of locking relay LR, conductor 252, motor magnet winding 279, conductor 268', contacts 2q-1q, switch set 265 of timing relay unit TR, conductor 267 to ground 266. This circuit through the winding 279 of motor magnet MN moves the armature of the motor magnet to the left FIG. 9, and positions the end of stepping pawl 281 so that it will engage one of the teeth of ratchet 289. As the arm 280 of the motor magnet moves to the left, it closes contacts 1r-2r and in so doing completes a circuit from junction 253 to ground 266, FIGS. 4 and 5 as follows: junction 253, contacts 2p-1p, switch set 246 of locking relay unit LR, conductor 252, contacts 1r-2r (now closed) conductors 275' and 275, winding 262b of timing relay unit TR to ground 266. This circuit through the winding 262b of the timing relay unit TR moves its switch set 265 to operative position breaking the current through winding 279 of the motor magnet MN. When the circuit of motor magnet MN has been broken the impeller spring 282, becomes effective to restore the armature arm to its initial position. The return movement of armature arm 280 causes stepping pawl 281 engaging one of the teeth in ratchet 289, to impart the requisite stepping movement to the wiper arms 285 and 286 and disk 287.

As the wipers 285 and 286 of the distant station selector alternately engage their respective mine contacts, the circuit from junction terminal 253 to ground 296 will be formed repeatedly to produce the required flow of current from terminal 253 to ground 266, through the motor magnet winding 279, along the alternate paths hereinbefore described, causing the distant station selector to continue its stepping movement until the mine contact m19 which is in circuit with ground 306 has been reached by the wiper arm 286, whereupon said arm will be stopped on the grounded mine contact, as will be hereinafter described. Assuming that none of the mine contacts are grounded, when wipers 285 and 286 reach home position h and h1, notch 290 in disk 287 will register with home position h2, thereby disconnecting the disk and ground 296 and disrupting the circuit from junction terminal 253 to ground 296 to stop the distant selector on the home position.

Inasmuch as the casemate selector CS is controlled by the distant selector, said casemate selector will likewise stop on the home position. If one of the mine contacts of the distant selector has been grounded the wipers 285 and 286 will continue to step to and lock on, the grounded mine contact until said ground has been eliminated, as will hereinafter appear. The operation of the casemate and distant selectors produces a pulsating current through the system which momentarily operates the switch sets of the various relay units. To prevent this movement of the switch sets completing the high potential firing power circuit to the distant selector, the guard relay unit 92 (FIG. 1) has the armature of its relay counterweighted as at 94a so that this unit will not respond to the action of the pilot relay unit until the latter has moved its switch set 71 to operated position and has permanently retained the set in this position.

The automatic selector at the casemate is adapted to step in coordinated sequence with the stepping movement of the distant station selector DS and to effect this operation several paths are made available to the current as it flows from junction 143e (FIGS. 2 and 4), to conductor 155, which as previously indicated is normally in circuit

with the junction terminal 253, at the distant station. One of the paths available to the current flow is as follows: junction 143e, conductor 213, winding 208 of motor magnet MM, conductors 215 and 214, motor magnet contacts 211 and 212, conductor 184, contacts 2n-1n of switch set 180 of impulsing relay unit P, conductor 183, a portion of winding 192 of synchronizing relay unit Q, conductor 155 to junction 253 (FIG. 3). Another path simultaneously available to the flow of the current from junction 143e is as follows: junction 143e, winding 208, conductor 188, contacts 5n-6n of switch set 180 of impulsing relay unit P, winding d of the impulse relay unit P, conductor 189, winding 192 of synchronizing relay unit Q to conductor 155 and thence to junction terminal 253 (FIG. 4).

The flow of current through winding 208 of the motor magnet MM along the paths defined, effects its energization and retracts armature arm 210. At the same time the current flowing through winding d of impulse relay unit P energizes and moves its switch set 180 to operated position. The operation of switch set 180 breaks the two paths through winding 208 of the magnet, one of which includes a part of winding 192 of synchronizing relay Q, the other of which includes the winding d of impulsing relay P and the entire winding 192 of synchronizing relay Q. In this connection it is to be noted that, as the operation of switch set 180 of impulsing relay P disrupts the circuit through a part of winding 192 of the synchronizing relay Q, a substitute circuit is provided by the engagement of contacts 4n and 6n of impulsing relay P, which circuit extends from conductor 143 through conductor 187, contacts 4n and 6n, winding d, impulsing relay P, and winding 192 of synchronizing relay Q to conductor 155 (see FIG. 4), thus inserting in the circuit the windings d and 192 of impulsing and synchronizing relays P and Q, respectively, as winding 208 of the motor magnet MM is cut out. Armature arm 210 of the motor magnet as it moves to its retracted position against the action of the retractile spring (not shown), breaks the circuit through the winding 208 by separating the contacts 211 and 212. When thus deenergized, the retractile spring (which is adapted to be connected to the armature arm 210), restores said arm to its original position, whereupon the circuits through the winding 208 from junction 143e to the conductor 155 are reformed. Movement of armature arm 210 to normal position by the spring (not shown) causes the stepping pawl (not shown) adapted to be carried by arm 210, to rotate shaft 207' of the contact bank sufficiently to move the wipers 204 to 207 ahead one step, as will be understood without further discussion. The sequence of operation of the casemate selector CS and the distant station selector DS, is arranged so that when the casemate selector CS has just stepped ahead the distant station selector DS has just retracted on the previous mine contact. As the current flows from junction 143e through winding 208 of the motor magnet MM to conductor 155, it passes through winding 192 of synchronizing relay unit Q and energizes said relay to move its switch set 195 to operative position. When in this position the contacts 1o-2o of switch set 195 are open and the circuit to the ground 199 which also includes winding 208, is broken. Unless broken the circuit to ground 199 would step the selector to its home position, as will hereinafter appear.

Assuming that the casemate and distant station selectors have left their home positions and are stepping in the required coordinated sequence and that wiper 286 of the distant station selector is about to contact mine contact m19, which as previously stated, is connected to the ground 306 by the impact of a vessel with the mine; when wiper 286 of the distant station selector engages mine contact m19 an electrical path will be established from junction terminal 253 (FIGS. 3 and 5), through the winding 243 of locking relay unit LR, wiper 286, contact m19,

conductors *n19* and *o19*, mine fuse 241, conductor *p19*, terminal 311 of mine assembly E, a portion of winding 302 of circuit-closing relay CR, conductor 308, contacts 2*s*-1*s* of switch 305, conductor 307 to ground 306. This path to ground causes the locking relay unit LR to move its switch set 246 to operated position, thereby breaking the circuit from junction 253 to ground 266 through the winding 279 of motor magnet MN and stopping the distant station selector on the grounded mine contact.

A steady current now flows through the entire system from the 110 volt direct current source, terminal 1 (FIG. 1), to junction 253 (FIG. 3), and from the latter, as just traced, through wiper 286 to the ground 306 (FIG. 5). This circuit which includes winding *d* of impulse relay unit P, winding 192 of synchronizing relay unit Q, winding 68 of pilot relay unit 67, winding 243 of locking relay unit LR, a part of winding 302 of circuit-closing relay unit CR, causes these units to move their switch sets to operated position, thereby effecting various circuit changes in the mine control assembly A, supervisory assembly B, distributing assembly C and mine assembly E. To indicate the nature of these changes, reference will be had to the assemblies in the order of their enumeration.

In regard to mine control assembly A, movement of switch set 71 of pilot relay unit 67 from its normal to operated position, opens contacts 1*c*-2*c* and closes contacts 2*c*-3*c* and 4*c*-5*c*. When contacts 1*c* and 2*c* have been opened the circuit from terminal 1 through winding 93 of the guard relay unit 92 to ground 96 will be broken, which releases switch set 95*a* and closes its contacts 1*e*-2*e*. As the circuit through winding 93 of guard relay unit 92 is broken, the circuit through light 28 will be disrupted thereby extinguishing said light. Closing contacts 2*c*-3*c* of switch set 71, pilot relay unit 67 and contacts 1*e*-2*e* of switch set 95*a*, guard relay unit 92, completes a circuit from terminal 1 through winding 99 of the firing power relay 98 to ground 104. The establishment of this circuit causes the firing power relay unit to move its switch set 102 to operated position closing its contacts 1*f* to 4*f* inclusive, and completing a circuit from the 600 volt power terminal 4 through winding 1*a* of the control relay unit 78 to ground 306 (FIGS. 1 and 6), which will herein-after be defined. As the circuit is completed from power terminal 1 to ground 104 (FIG. 1), through contacts 2*c*-3*c* of switch set 71 and contacts 1*e*-2*e* of switch set 95*a* and winding 99 of firing power relay unit 98, a circuit is also formed through the red light 23 from power terminal 1 to ground 25' which is connected to terminal 25 of said light. Glowing of the red light 23 notifies the operator that the firing power circuit has been completed. Operation of switch set 71 of pilot relay unit 67 closing contacts 4*c*-5*c*, likewise completes a circuit from the power terminal 6 (FIG. 1) to power outlet terminal 114 (FIG. 2) through bell 115 and red light 116 of the alarm unit H. This bell will continue to ring until the operator opens the control switch 117.

The high potential firing power flowing through winding 1*a* of control relay unit 78 causes said relay to move its switch set 81 to operative position which opens contacts 1*d*-2*d* and closes contacts 3*d*-4*d* and 5*d*-6*d*. As contacts 1*d*-2*d* are opened and contacts 3*d*-4*d* closed, the 110 volt operating power from terminal 1 (FIG. 1), is connected to ground 88 (FIG. 1) through resistance 90 thus removing all operating power from the shore cable Y. Closing the contacts 5*d*-6*d* of switch set 81 completes a circuit from power terminal 6 to the power outlet terminal 114 through bell 115 and light 116 of alarm unit H.

From the preceding it will be apparent when wiper 286 of the distant station selector stopped on mine contact *m19*, pilot relay unit 67 of assembly A functioned—

(a) To extinguish white light 28, break the circuit through winding 93 of guard relay unit 92 and release its switch set 95*a*;

(b) To complete a circuit through red light 23 and through the winding 99 of firing power relay unit 98 moving its switch set 102 to operated position and completing a firing power circuit through winding 1*a* of control relay unit 78 to shore cable Y, and further that the completion of the firing power circuit through winding 1*a* of control unit 78 operated the switch set of said unit to remove the 110 volt direct current operating power from the shore cable and to connect said power to the ground 88.

10 With reference to the supervisory assembly B and having in mind the order of operation of the casemate and distant station selectors, wherein casemate selector CS retracts and steps ahead, while the distant station selector DS retracts and then steps ahead, it follows that the wipers 15 204 to 207 of the casemate selector will be on contacts *a19*, *b19*, *c19* and *d1*, as wiper 286 of the distant station selector engages contact *m19*, hence as the current flows from terminal 1 (FIG. 1) to ground 306 (FIG. 3), it traverses winding 208 of the motor magnet MM and then 20 winding *d* of impulse relay unit P, causing said unit to move its switch set 180 to operative position which opens contacts 1*n*-2*n*, closes contacts 2*n*-3*n*, opens contacts 5*n*-6*n* and closes contacts 4*n*-6*n*.

As contacts 1*n*-2*n* are opened the circuit through winding 298 of motor magnet MM of the casemate selector is broken, thus holding the wipers 204 to 207 of the casemate selector on the contacts *a19*, *b19*, *c19* and *d1*. As contacts 1*n*-2*n* are opened the contacts 4*n*-6*n* are closed, which establishes a path for the current from 30 junction 143*e* through conductor 187, contacts 4*n*-6*n* to winding *d* of the impulse relay unit, and retains the switch set in its operative position as long as the steady flow of current to ground continues. Opening contacts 5*n*-6*n*, 35 breaks an alternate path for the current from junction 143*e* through the winding 208 of motor magnet MM along conductor 188 through contacts 5*n*-6*n* to the winding *d*.

From the winding *d* of the impulse relay unit P the current flows through conductor 189 and winding 192 of 40 synchronizing relay unit Q to junction terminal 253 (FIG. 3), from whence it passes to ground 306, as previously state. The current transversing winding 192 of the synchronizing relay unit Q causes said unit to move its switch set 195 to operative position which disrupts the 45 circuit to ground 199 through winding 208 of the motor magnet, and prevents the casemate selector stepping to home position. At the time switch set 195 opens contacts 1*o*-2*o* to the ground 199, it also opens the contacts 3*o*-4*o* which normally provide an auxiliary path for the 50 45 volt signal current when the check key K is utilized for checking purposes. Contacts 5*o*-6*o* when closed shunt part of the winding 192 of synchronizing relay Q for the purpose of increasing the flow of current by reducing 55 resistance.

It will thus be seen that when wiper 286 of the distant station selector engages contact *m19* to establish the circuit to ground 306, a steady flow of current through the system breaks the circuit of motor magnet MM, holds the wipers 204 to 207 of the casemate selector on contacts *a19*, *b19*, *c19* and *d1*, and causes the impulse relay unit P and synchronizing unit Q to function for the purpose hereinabove stated.

In regard to the assembly C at the distant station (FIG. 3), when wiper 286 engages contact *m19* the flow of the 65 current from junction terminal 253 through winding 243 of locking relay unit LR to ground 306, through wiper 286, causes said locking relay unit LR to move its switch set 246 to operated position which opens contacts 1*p*-2*p*, 3*p*-4*p* and 6*p*-7*p* and closes contacts 2*p*-4*p* and 5*p*-7*p*. Opening contacts 1*p*-2*p* disrupts the circuit through winding 279 of motor magnet MN to ground 266 and thus locks the wiper on contact *m19*.

Closing contacts 2*p*-4*p* provides a substitute path for 75 the current from junction terminal 253 to ground 306

through contacts $2p-4p$, conductors 249 and 248, winding 243 of locking relay unit LR, wiper 286, contact $m19$, cutting out resistance 248' and leakage resistance to ground 256. Closing contacts $5p-7p$ and opening contacts $6p-7p$ breaks the circuit from terminal 253 to ground 266, through the home contact h of the distant station selector, as previously explained. Manifestly when wiper 286 of the distant station selector DS engages contact $m19$, locking relay unit LR functions to stop the selector on the grounded mine contact, as will be apparent without further discussion.

In regard to the mine assembly E, as the current flows from junction terminal 253 through wiper 286, mine contact $m19$, conductors $n19$, $o19$, fuse 241, conductor $p19$, terminal 311, and a part of winding 302 of the circuit-closing relay unit CR to ground 306; relay unit CR functions to elevate the armature arm 304 and in so doing engages contacts 3s and 304'. As the upward movement of arm 304 continues, contact 1s will be elevated to separate contacts 1s-2s and at the same time elevate member 318 sufficiently to permit bell 317 to assume its normal position, thus disarming the mine. As the contacts 1s-2s are brought into engagement, a path is formed for the current through winding 302, conductor 308, contacts 2s-1s, conductor 307 to ground 306.

Firing circuit.—With the completion of this last mentioned circuit, the system is now conditioned for the passage of the firing current from terminal 4 (FIG. 1), to ground 306 (FIG. 3). The path of the firing current to ground shown in FIG. 6, is as follows: 600 volt power terminal 4, conductor 51, contact 44b, of firing switch 43, contact 44e, conductor 54, contacts 5b-4b of switch set 60, conductor 66, contacts 4f to 1f inclusive, switch set 102, conductor 91, winding 1a of control relay unit 78, conductor 83, winding 68 of pilot relay unit 67, conductor 84, ballast resistance Z, shore cable Y, junction terminal 253, contacts $2p-4p$, conductors 249 and 248, winding 243, conductor 250, wiper 286, contact $m19$, conductors $n10$, $o10$, fuse 241, conductor $p19$, terminal 311, winding 302 of the circuit-closing relay unit CR, conductor 312', resistance 313, conductor 314, firing relay winding 321', conductor 337, contact 3s, dependent contact 304', contact 1s, conductor 307, ground 306. The passage of the firing current through winding 321' of the firing relay unit FR moves its switch set to operated position and thereupon completes a circuit from terminal 311, assembly E, to ground 306, through detonators 327 and 322 respectively. This circuit is as follows: terminal 311, conductors 312 and 325, contact 1t-2t, switch set 321, conductor 328, terminal 326', detonator 327, terminal 329 of said detonator, conductors 330 and 333, contacts 3t-4t, conductor 336, winding 321' of firing relay unit FR, conductor 337, contact 304', contact 1s, conductor 307 to ground 306.

In this connection, it is to be noted that owing to the high voltage of the firing power, in addition to its passage to ground 306, via contacts 3s-1s and conductor 307, said current may also reach ground 306 via conductor 310, neon tube 309, conductors 319 and 307 to ground 306. The passage of the 600 volt firing power through the detonators fires the mine, as will be understood without further discussion.

As the mine is fired the fuse 241 in the mine circuit is usually ruptured and when this occurs the path to ground for the firing power is eliminated. The elimination of this path reduces the flow of current through winding 1a of the control relay unit 78 and winding 68 of the pilot relay unit 67. Material reduction in the flow of the current through winding 68 of the pilot relay unit 67 permits its switch set 71 to return to normal. The contacts of relay switch set 71 being restored to their original position, break the circuit through the winding of the firing power relay and reform the circuit through the winding of the guard relay unit 92 which opens the firing power circuit and removes all current from the

shore cable. Reduction of the flow of the current through winding 1a of control relay unit 78 does not release the switch set 81 of said unit by virtue of the circuit to ground 88, through winding 2b, which retains the switch set 81 in operative position until the firing switch 43 has been opened.

When start key 56a of the start key switch unit 56 is depressed and then released, contacts 1a-2a of switch set 56b will be opened and then closed, to make and break the 110 volt operating circuit. Normally disrupting the operating circuit in this manner, permits the various members of the system, which have been moved to operative position, to return to normal, and reforming the circuit causes the selectors to start their stepping movement. Therefore to prevent the unintentional application of firing power to the mines after one has been fired, a safety circuit is provided in connection with the firing switch 43 so that when said switch is closed, the safety circuit becomes effective.

The safety circuit established by firing switch 43 is as follows: terminal 1 (FIG. 1), conductor 74, conductor 45, terminal 34a of operating switch 33, terminal 34c of said power switch 33, conductor 17, anode and cathode 16 and 15 respectively of diode 14, secondary winding 9 of transformer 7, conductor 53, terminal 44d of firing switch 43, terminal 44a of said firing switch, conductor 49, conductor 50, terminal 50a of terminal block 106, conductor 50b, terminal 50c (FIG. 2), conductors 140 and 139', contact 6h of group jack J, contact 5h of said jack, conductor 138', resistance 139, conductor 138, terminal 59c, conductor 59b (FIG. 2), terminal 59a, terminal block 106, contacts 3d-4d of switch set 81, conductors 22 and 82, winding 2b, control relay unit 78, conductor 89, resistance 90, ground 88. This circuit retains switch set 81 of control relay unit 78 in its operated position until firing switch 43 has been opened to break the circuit and permit switch set 81 to return to its normal position, whereupon contacts 1d-2d of said switch set 81 will connect terminal 1 of the operating power with shore cable Y, as previously described.

After firing switch 43 has been opened, the depression and release of start key 56a, will disrupt and then reform the operating circuit to cause the selector at the distant station to step to and stop on the home position. Should the distant station selector, instead of stopping at the home position, continue to step and return to the contact $m19$ of the fired mine, the casement operator would be informed that fuse 241 of mine M19 was not ruptured when the mine was fired, owing to the formation of a gas bubble at the end of the mine cable and the consequent collapse of firing power during the explosion of the mine. The formation of the gas bubble decreases the flow of current through winding 68 of the pilot relay 67 (FIG. 1), to an extent sufficient to release its switch set 71 and permit the return of said switch set to normal position. The return to normal of switch set 71 kills the firing power relay 98 and energizes the guard relay 92 which shuts off the firing power to the shore cable thus causing a collapse of the power necessary to rupture the mine fuse.

To clear fuse 241 and permit the distant station selector to return to home position, the operator at the casemate depresses clearing key 60a. Depression of key 60a (FIG. 1), shifts its switch set 60 to operated position and closes contacts 1b-2b and 3b-4b and opens contacts 4b-5b. Closing contacts 3b-4b of clearing switch set 60b establishes a circuit from the 250 volt terminal 110 (FIG. 2), through fuse 241 to grounded cable at the distant station as follows: terminal 110, conductor 150, contacts 1j-2j of milliammeter key L, conductors 152-151 to contacts 8k-7k of test key M, conductor 171 to terminal 65c, conductor 65b, terminal 65a of terminal block 106, conductor 65, contacts 3b-4b of switch set 60b, conductor 66, contacts 4f to 1f inclusive, switch set 102 of the firing power relay 98, conductor 91, winding 1a of control relay unit 78, con-

ductor 83, winding 63 of pilot relay unit 67, conductor 84, ballast resistance Z, shore cable Y, junction terminal 253, contacts 2p-4p, switch set 246 of locking relay LR, conductors 249 and 248, winding 243 of locking relay unit LR, conductors 250 and 291, wiper 286, mine contact m19, conductors m19-o19, fuse 241 to the grounded cable.

To prevent unintentional application of the 250 volt clearing power to the mines, after a fuse has been ruptured, a safety circuit is provided in connection with the switch set 60 of clearing key 60a, by means of which switch set 81 of control relay unit 78 is retained in operated position until the switch set 60 of the clearing key unit has been restored to its normal position. By the provision of this circuit, operation of the start key 56a will have no effect upon the distant station selector until the clearing key has been restored to its normal position. This safety circuit is as follows: terminal 1, conductors 74-45, terminal contacts 34a-34c of power switch 33, conductor 17, anode and cathode 16 and 15 of diode 14, secondary winding 9 of transformer 7, conductors 53, 57 and 64, contacts 2b-1b of switch set 60, conductor 63, conductor 50, terminal 50a of terminal block 106, conductor 50b, terminal 50c, through group jack J to terminal 59c (FIG. 2), conductor 59b, terminal 59a of terminal block 106, conductor 59, contacts 3d-4d of switch set 81, conductors 22 and 82, winding 2b of control relay unit 78, resistance 99 to ground 88. This circuit keeps the 110 volt direct current operating power off the shore cable Y and in connection with ground 88. Depression and release of start key 56 will then permit the selectors to step to and stop on the home position and restores the system to its alert condition.

From the foregoing, it should be apparent, when a vessel traversing mine field D, strikes a mine, the impact automatically establishes ground 306, which causes both the distant station and casemate selectors to step from their home positions and to continue stepping in coordinated sequence until one of the wipers of the distant station selector engages the contact in circuit with the automatically established ground, whereupon there is formed an electrical path to said ground through the contact engaged wiper of the distant station selector, for a steady flow current, which prevents further operation of the casemate and distant station selectors, effects certain signal changes at the casemate, arms the grounded mine and conditions the system for the passage of a 600 volt firing current adapted to flow through the contact engaged wiper arm of the distant station selector, and thence through the mine detonators to ground 306 which fires the mine and simultaneously removes all power from the shore cable.

Let it now be assumed that the system is on the alert, the casemate and distant station selectors on their home positions and the components of mine assembly E in the positions shown in FIGS. 2 and 3 of the drawings. To fire mine M19 from the casemate, mine control key mk19 is depressed which engages contacts 1m-2m and places the 250 volt direct current terminal 110 (FIG. 2) in circuit with contact a19 of the locking level A—A of casemate selector CS. Start key 56a (FIG. 1) of the start key switch unit 56 is depressed and then released to open and close contacts 1a-2a to break and reform the 110 volt direct current operating circuit. This momentary disruption of the operating circuit allows switch set 265 (FIG. 3) of the timing relay unit TR to return to its normal position, so that when the contacts 1a-2a of the start switch unit 56 (FIG. 1), are restored to their original position to reform the operating circuit, the flow of current through the motor magnets MM and MN of the casemate and distant station selectors, causes the selectors to leave their home positions and to step in coordinated sequence toward the selected mine M19, as previously described.

In view of the sequence of operation of the casemate and distant station selectors, when wiper 204 of the casemate selector reaches mine contact a19 250 volts

will be placed on the shore cable through wiper 204 of the casemate selector. For the purpose of this discussion the voltage referred to as "locking power" will be considered as available at junction 253 (FIG. 3). As the casemate selector CS engages contact a19, the distant station selector will be in retracted position on the previous mine circuit, that is to say, armature arm 280 of motor magnet MN will have been moved downwardly to engage contacts 1r-2r of said motor magnet, so that the first surge of locking power through junction terminal 253 to ground 266 via contacts 1p-2p of switch set 246, conductor 252, contacts 1r-2r, conductors 275' and 275, relay winding 262b of timing relay TR to ground 266, energizes the timing relay TR and causes its switch set 265 to move to operative position which opens contacts 1q-2q of switch set 265 and disrupts the operating circuit through motor magnet MN, whereupon since the armature arm of the motor magnet is in retracted position, it is restored to its initial position by spring action (FIG. 9), thus moving wiper 285 to contact m19. The 250 volt locking power thrown on the shore cable and available at terminal 253, when wiper 204 of the casemate selector engaged contact a19 of locking level A—A, will be to a large extent dissipated through the leakage paths to the grounds 254 and 249 respectively, so that notwithstanding the fact that wiper 285 of distant station selector DS at the time is in engagement with contact m18, the potential available at said mine contact will not be high enough to overcome the resistance to ground 306 interposed by the neon tube 309, consequently this voltage will not stop distant station selector DS on contact m18. When the distant station selector has stepped ahead under spring action as stated, the armature arm 280 of motor magnet MN opens contacts 1r-2r and breaks the circuit through winding 262b of the timing relay TR to ground 266. As this relay is slow acting, switch set 265 will not return to its normal position immediately, but will be held in operated position for a short time interval. During this interval the 250 volt locking power barring leakage paths to grounds 254 and 249 has one important path to ground 306 from distributing terminal 253 as follows: junction terminal 253, conductor 247, resistance 248', conductor 248, winding 243 of locking relay LR, conductor 250, conductor 291, wiper 286, contact m19, conductors n19-o19, fuse 241, conductor p19, junction terminal 311 of mine assembly E, conductor 312, winding 302 of the circuit closing relay CR, conductor 312', resistance 313, conductor 314, winding 321' of firing relay FR, conductor 337, contact 3s, conductor 310, neon tube 309, conductors 319 and 307 to ground 306. Along this path the potential available at the neon tube 309 is approximately 70 volts which is sufficiently above the breakdown point of the tube to permit the circuit to ground 306 to be completed. This circuit through winding 243 of locking relay LR, causes said relay to move its switch set to operative position, separating contacts 1p-2p which cuts out winding 279 of the motor magnet MN and locks the wiper 286 on contact m19. When switch set 246 moves to operated position its contacts 2p-4p are engaged to reform the circuit from junction terminal 253 to ground 306, via contacts 2p-4p and conductors 249 and 248 to winding 243, instead of the path initially provided through conductor 247, resistance 248', conductor 248 and locking relay winding 243, thus cutting out resistances 256 and 248' (FIG. 3).

In addition to operating the locking relay unit LR, the locking power circuit from junction terminal 253 to ground 306 causes the circuit closing relay CR and the firing relay FR in assembly E, to function. When circuit closing relay CR energizes its armature arm 304 moves upwardly and engages contacts 3s and 1s of switch set 305 through the dependent member 304', thus supplementing the circuit to ground 306 via the tube 309 with the circuit via conductor 307.

When the firing relay unit energizes, its switch set moving to operative position closes contacts 1t-2t and 3t-4t and completes a circuit from terminal 311 to ground 306 through the mine detonators 327 and 332, via conductors 312 and 325, contacts 1t-2t and 3t-4t, conductor 336, winding 321' of the firing relay, conductor 337, contacts 3s-1s, switch set 305, conductor 307 to ground 306. The completion of this circuit establishes a path for the 600 volt firing power through the detonators 327 and 332 and fires the mine.

In view of the above, it will be evident when mine control key *mk19* at the casemate is depressed and the start key 56a of the start key switch unit 56 depressed and then released, the selectors CS and DS will step from their home positions and continue to step to the selected mine whereupon wiper 286 of the distant station selector will be locked on the contact *m19* of the selected mine to establish a path for the 600 volt firing power, which, traversing the detonators of the mine effects its explosion.

Synchronizing circuit.—In the course of the operation of the instant system the coordinated sequence of operation of the distant and casemate selectors sometimes becomes disrupted. In this event ground 296 (FIGS. 3 and 7) being in circuit with junction 253, through disk 287 of the distant selector, there is a flow of current through the winding 279 of motor magnet MN to ground 266. This current energizes winding 279 of motor magnet MN and operates its armature arm 280 to close contacts 1r-2r and complete a circuit to ground 266, through the winding 262b of timing relay unit TR. This circuit energizes the timing relay and moves its switch set 265 to operated position, thus disrupting the circuit through motor magnet MN. As the circuit through the motor magnet MN is disrupted, spring action restores armature 280 to its original position, stops the selector and reforms the circuit through the winding of the motor magnet MN. These circuits are repeated until the distant station selector reaches its home position at which point the notch 290 of disk 287 overlying contact *h2* cuts out ground 296 to stop the selector on the home position with wipers 285 and 286 in engagement with contacts *h* and *h1* respectively.

As the wipers 285 and 286 engage the contacts *h* and *h1* of the distant station selector, two paths will be available for the flow of the current from junction terminal 253 to ground 266. One of these paths is as follows: terminal 253, conductor 247, resistance 248', conductor 248, winding 243 of locking relay unit LR, conductors 250 and 291, wiper 285, conductor 261, contact 7p of switch set 246, contact 6p, conductor 260, winding 262a of timing relay unit TR, conductor 272, resistance 273, conductor 274, junction 271, resistance 276, conductor 275, winding 262b of timing relay TR to ground 266. The remaining available path from junction 253 to ground 266 is as follows: junction 253, contact 2p of switch set 246, contact 1p, conductors 252 and 269, contacts 3q-4q of switch set 265, conductor 270, contact *h1*, wiper 286, conductor 298, wiper 285, contact *h* and from this contact just traced to ground 266. The circuit through the windings 262a and 262b causes the switch set 265 to move to operated position which breaks the circuit to ground 266 via conductors 252, 269, contacts 3q-4q of switch set 265, conductor 270, contact *h1* of the distant station selector, wiper 286, conductor 298, wiper 285, contact *h* of the distant station selector. The circuit from contact *h* of the distant station selector through the windings 262a, 262b remains effective to retain switch set 265 in operated position which disrupts the circuit through the winding 279 of motor magnet MN, and thus makes it impossible for the selector to step until the switch set 265 of timing relay TR, has been released by the deenergization of its windings, as will be readily understood without further discussion.

Meanwhile at the casemate station (FIGS. 2 and 7), a ground 199 is established which causes a flow of cur-

rent from terminal 1 (FIGS. 1 and 7) to junction 143e, conductor 143, conductor 143b, winding C of impulsing relay P, resistance 190, conductor 145, contacts 6i-7i of check key unit K, conductor 146, wiper 205, serving synchronizing level B—B of casemate selector CS, contact *b2*, conductor 220, conductor 168, contacts 3k-4k of test key M, conductor 169, contacts 4m-3m of mine key MK19, conductor 174, contacts 4m-3m of mine key MK1, conductors 173 and 196, contacts 1o-2o of switch set 195 of the synchronizing relay unit Q, conductor 200 to ground 199. Current flowing through the winding C of the impulse relay unit P causes the switch set 180 of said unit to remain in operative position, closing the circuit from junction 143e through the winding 208 of motor magnet MM, conductors 215 and 214, interrupter contacts 211 and 212 of the motor magnet, conductor 184, contacts 2n-3n of switch set 180, resistance 186 and conductor 145, thence to ground 199, as previously described. This circuit energizes the motor magnet MM and actuates its armature arm 210 to break the circuit through contacts 211 and 212 to ground 199. When this circuit has been broken, arm 210 returns to its initial position stepping the selector and reforming the circuit through interrupter contacts 211 and 212, and this will be repeated until the casemate selector reaches the home position whereupon it will be stopped, thus placing the wipers of the casemate selector and those of the distant selector on the home positions.

Test circuit.—For the purpose of adjusting the ballast resistance Z (FIG. 1) so that the total resistance of the shore cable and the ballast resistance is 200 ohms, a test circuit is provided. To render this circuit effective switch key 149 of milliammeter key L (FIG. 2) is moved to the right into the position designated operated (FIG. 2), which closes contacts 3j-4j and 6j-8j, opens contacts 7j-8j and includes the milliammeter and voltmeter MA and V in the circuit under test. After this adjustment of the milliammeter key L, switch member 150a of test key M is moved to the right which opens contacts 3k-4k of switch set 150b and closes contacts 1k-2k, thus opening the circuit to ground 199 and connecting the 250 volt direct current terminal 110 with contact T, level A—A of the casemate selector via conductors 150, 167', resistance 167a, conductor 167, test key contacts 2k-1k, conductor 165, contact T. Start key 56a of start key unit 56 (FIG. 1) is now depressed and released to open and to close the 110 volt operating circuit through the system. Opening and closing the 110 volt operating circuit in this manner restores the operated elements of the system to their normal positions and causes the distant station and casemate selectors to step from their home positions and continue their stepping movement until the distant station selector engages testing contact T and establishes a circuit to ground 292 through the resistance 294. As ground 292 is formed the current flowing from junction 253 through winding 243 of relay unit LR, wiper 286, contact T to ground 292, causes locking relay unit LR to move its switch set 246 to operated position, breaking the circuit from junction 253 to ground 266 through winding 279 of motor magnet MN and thus stopping the selector on the contact T, as will be understood without further discussion.

At the casemate, when ground 292 is established through the distant station selector, a steady flow of current traversing the winding *d* of impulse relay P (FIG. 2) causes said relay to retain switch set 180 in operated position which opens contacts 1n-2n and 5n-6n of switch set 180 and closes its contacts 2n-3n, 4n-6n disrupting the paths available to the current from junction 143e to conductor 155 through winding 208 of motor magnet MM. Breaking the circuit through winding 208 of motor magnet MM in this manner steps the casemate selector and retains wiper 204 on testing contact T. When wiper 286 of the distant station selector (which it will be recalled lags the casemate selector) engages con-

tact T, a 250 volt circuit will be established from terminal 110 (FIG. 1) to ground 292 (FIG. 3) through the milliammeter MA and voltmeter V. Milliammeter MA should afford a reading of approximately 67 milliammeters and if this is not the case the ballast resistance Z should be adjusted until this reading is obtained.

To test each mine circuit instead of actuating the test key M, as outlined above, the mine key MK of the mine circuit to be tested is depressed to connect the 250 volt direct current terminal 110 with one of the contacts a1 to a19, locking level A—A of casemate selector CS so that 250 volts is available at each of the contacts a1 to a19 inclusive, as previously described. After the proper mine key has been depressed, start key 56a of start key unit 56 is likewise depressed and then released to open and close the 110 volt operating circuit. This operation of the start key causes the casemate and distant station selectors to step from their home positions and to continue stepping until one of the wipers of the distant station selector engages the contact of the mine circuit to be tested. When this occurs, locking relay unit LR functions to operate its switch set and thus lock the system on the mine circuit under test. After the mine key has been released the milliammeter should give a reading of approximately 60 milliammeters.

Mine signaling circuit.—To inform the casemate operator with respect to the particular mine upon which the system has locked, nineteen mine signaling lamps are provided in connection with assembly B (FIG. 2) and these are caused to function selectively through contacts c1-c19 of level C—C casemate selector CS which are served by wiper 206. When wiper 206 is on contact c1 a circuit will be established from the 45 volt alternating current terminal 113 as follows: terminal 113 (FIG. 2), conductor 128, contacts 8j-7j of center jack I, conductor 127 contacts 4i-3i of check key K, conductor 143' wiper 206, contact c1 of signal level direct of the casemate selector, conductor 176b, conductor 176a, signal lamp ms1, conductor 175a, conductor 175, conductor 147, contacts 8i-9i of check key K, conductors 179 and 179' to 45 volt terminal 112.

Whenever the distant station selector stops on one of its mine contacts m1 to m19 and since the casemate selector has stopped on a corresponding contact, a circuit will be formed through the mine signaling lamp connected with the contact upon which wiper 206 of the casemate selector has stopped, as will be understood without further discussion. When the distant station selector is on the home position, wipers 206 and 207 of the casemate selector will be on contacts designated H3 and H4, circuits will be established from terminal 113 to terminal 112 through contacts 8g-7g, wipers 206 and 207 and mine signal lamp ms20 to indicate that both the distant station and casemate selectors are on their home positions. To advise the casemate operator that the 600 volt firing power has been applied to the assembly A, a red signal 38 (FIG. 1) is provided, so that when the operator at the power unit (not shown) throws the switch controlling the application of firing power to assembly A, said switch (not shown) will complete a circuit from terminal 2 to terminal 6 through the red signal 38 via conductor 42 (FIG. 1), terminal 39 of signal 38, terminal 40, conductors 41 and 76, conductor 11. With signal 38 glowing the operator is advised that 600 volts firing power is available at the switch 43.

In the normal operation of this system, the casemate selector stepping in coordinated sequence with the distant station selector, causes the mine signal lamps to be lighted in numerical progression from ms1 through ms19, as the wiper 206 of the casemate selector engages the contacts c1 to c19 of the selector level designated "signal level direct," and as the distant station wipers successively engage the contacts m1 through m19 of the mine levels. However, to enable the casemate operator to recheck the mines in their reverse order, that is to check back from

mine m19 to m1, the casemate selector is provided with a row of contacts D—D designated "signal level check" (FIG. 2), served by wiper 207, the contacts and wiper being in electrical relation with 45 volt terminals 112 and 113 through lamps ms19 to ms1 and check key K.

In this level the contacts, unlike those in the remaining levels of the casemate selector, progress numerically in a counterclockwise direction from d1 to d19, the contact d1 in the illustrated embodiment being connected to conductor 176a, which conductor is also connected via conductor 176b with contact c1 of the level designated "Signal Level Direct" while contact d19 of the contacts designated "Signal Level Check" is connected via conductor 225 to conductor 177n which conductor is also connected with contact c19 of the contacts designated "Signal Level Direct." By connecting the contacts of level D—D in this manner, when key 142a of check key K is moved to the left, switch member 142b will be actuated to the right which opens contacts 3i-4i and closes contacts 4i-5i, to permit the establishment of the various signal lamp circuits from 45 volt terminal 113 to 45 volt terminal 112 through lamps ms19 to ms1.

In the illustrated embodiment of this invention the connections to the contacts of level D—D have been omitted with exception of those two contacts d19 and d1. For the purpose of this disclosure it is deemed sufficient to trace the circuit of but one of these two contacts to wit: terminal 113, conductor 128, contacts 8g-7g of center jack I, conductor 127, contact 4i of switch set 142b, contact 5i, conductor 144, wiper 207, contact d19, conductors 225 and 177n, signal lamp ms19, conductor 175, conductor 147, contacts 3o-4o of switch set 195 of synchronizing relay unit Q, conductor 148, conductors 179 and 179' to terminal 112. Assuming the remaining contacts d18 to d1 to be similarly connected, it will be apparent that as the wiper 207 proceeds in a clockwise direction the signal lamps will be illuminated in the order ms19 to ms1, as will be understood without further discussion.

The level D—D designated "signal level check" gives a result similar to that which would be obtained if the wiper 206 serving "signal level direct" after moving in a clockwise direction to its home position H3 and successively engaging the contacts c1 through c19 reversed its direction of movement and proceeded in an anti-clockwise direction to engage the contacts c19 to c1. In other words, in the absence of level D—D to check, for instance, mine M19, the contact end of wiper 206 serving level C—C after leaving its home position H3, would have to travel through an angle of 180° and then over mine contacts c1 to c19, whereas by the provision of the level D—D the wiper 207 serving the contacts d19 to d1 travels over but five contacts to engage contact d19 and cause the illumination of signal lamp ms19 which indicates that wiper 206 of the distant station selector is on contact m19 in circuit with mine M19, thus affording a rapid recheck of the mines in the reverse order.

In conclusion, it will be seen that after the instant system has been placed on the alert, a vessel traversing the mine field and striking one of the mines will, through the operation of the distant station selector, establish a path for a high potential current which passing through the mine detonators, fires the mine; that the mines may be selectively fired from the casemate; that every factor of safety to prevent premature mine explosion has been resorted to and that the casemate operator has been furnished with signals both visible and audible which provide at all times an exact knowledge of the electrical status of the system.

Having described our invention, what we claim as new and wish to secure by Letters Patent is:

1. A submarine mine system comprising a casemate control assembly, a distant station assembly including a submerged mine field and means in electrical relation with said respective mines of said mine field for controlling

their detonation of said mines, said means including a normally disrupted path to ground adapted to be established by mine impact, a single path of electrical distribution between the assemblies, and means for automatically firing any of the mines in said field on impact, said means including a distant station automatic selector having selective positions including a home position, and means in connection with the selector for maintaining the latter normally inoperative and on its home position until said path to ground has been established, and additional means controlled by mine impact for stepping said selector to one of its selective positions.

2. A submarine mine system comprising a casemate control assembly, a distant station assembly including a series of submerged mines and means in electrical relation with the respective mines for controlling their detonation, said means including a normally disrupted path to ground adapted to be established by mine impact, a single path of electrical distribution between the assemblies, and means for selectively firing any of the said series which has been sufficiently tilted by impact, said means including a distant station automatic selector having a series of selective positions and a home position, means for maintaining the selector normally inoperative and on its home position until said path to ground has been established, and additional means controlled by mine impact for stepping the selector to one of its selective positions.

3. A submarine mine system comprising a casemate control assembly, a distant station assembly including a series of mines, and means in connection with each mine for establishing a ground when a mine has been struck, a single path of electrical distribution between the assemblies and means to automatically fire any of the mines on impact, said means including a distant station automatic selector having selective positions connected to the respective mines and a home position, means for maintaining the selector normally inoperative and on its home position until said ground has been established by mine impact, and additional means for stepping said selector to one of its selective positions, said selective position being determined by the establishment of said ground on one of the mines.

4. A submarine mine system comprising a casemate control assembly, a distant station assembly including a series of submerged mines and means in connection with each mine to establish a ground by mine impact, a single path of electrical distribution between the assemblies, means to automatically fire any of said mines by impact, said means including a distant station selector situated in the midst of the mines, said selector having a series of selective positions connected with the respective mines, and including a home position, connected with a ground, means for maintaining the selector normally inoperative and on its home position until said ground has been established by mine impact, and additional means to step the selector from its home position to one of its selective positions, said selective position being determined by the mine which has been grounded by impact.

5. A submarine mine system comprising a casemate control assembly, a distant station assembly including a series of submerged mines, each mine including a mine assembly providing a normally open path to ground, and means in each of said paths and operated by impact to close said path to ground, a single conductor interconnecting the assemblies and providing a path of electrical distribution therebetween, means at the casemate assembly for impressing operating and firing power on said conductor, operating and firing circuits at the distant station and connected with said conductor, means for effecting a group connection of said normally open paths to ground with the operating circuit and additional means for disrupting said group connection when any of said open paths has been closed and to connect said closed path with the firing circuit.

6. A submarine mine system comprising a casemate control assembly, a distant station assembly including a series of submerged mines, each mine embodying a normally open path to ground, a single conductor interconnecting the assemblies and providing a path of electrical distribution therebetween, a source of operating power and a source of firing power connected with said conductor, an operating circuit and a firing circuit at the distant station and supplied with operating and firing power from said conductor, means at the distant station for effecting a parallel group connection between the operating circuit and the respective mine paths to ground, and means for disrupting said parallel group connection and selectively connecting the respective mine paths with the firing circuit.
7. A submarine mine system comprising a casemate control assembly, a distant station assembly including a series of submerged mines, each mine embodying a normally open mine circuit to ground, a single conductor interconnecting the assemblies and providing a path of electrical distribution therebetween, a source of operating power, a source of firing power at the casemate assembly, said operating and firing power being connected with said conductor, an operating circuit and a firing circuit at the distant station assembly, both of said circuits being supplied from said conductor, means for simultaneously connecting the mine circuits in parallel with the operating circuit, means for maintaining this connection until one of the normally open mine circuits has been closed, means for disrupting the group connection of the mine circuits with the operating circuit and selectively connecting said mine circuits with the firing power when one of said mine circuits has been closed, an impact operated mechanism in each of said mine circuits for closing said circuit when a mine has been struck.
8. A submarine mine system comprising a casemate control assembly, a distant station assembly including a series of submerged mines, each mine embodying a normally open circuit to ground and means in said circuit for closing the latter when a mine has been struck, a single conductor extending between the assemblies, and providing a path of electrical distribution therebetween, means at the casemate assembly for impressing an operating power and a high potential firing power on said interconnecting conductor, a firing circuit and an operating circuit at the distant station assembly, said circuits being supplied with operating and firing power from said conductor, an automatic selector at the distant station comprising a stepping mechanism, the latter being included in said operating circuit, a pair of wipers and a rotatable metallic disk simultaneously operated by said stepping mechanism, means for normally connecting the mine circuits of the respective mines in parallel with the operating circuit through said disk and wipers, and means controlled by the impact mechanism in the respective mine circuits whereby when a mine has been struck, the parallel connections of the mine circuits will be broken, and said circuits selectively connected with the firing circuit to fire the mine.
9. A submarine mine control system comprising a distant station including a group of submerged mines, a distributing assembly situated in the midst of the mines and controlling the distribution of electrical energy thereto, a mine circuit and a ground in connection with each mine, impact operated means for connecting the mine circuit with the ground, an automatic selector in the distributing assembly, said selector having a home position and a series of selective positions, corresponding in number to the number of mines of the mine group, means interconnecting said positions with the mine circuits of the respective mines, an operating circuit for said selector, means included in said circuit and coacting with the selector for normally maintaining the latter on its home position, additional means in said operating circuit to step said selector from its home position when a ground has been

formed on one of the mine circuits, a stepping circuit in connection with the operating circuit and said selector to step said selector to a selective position after it has stepped from the home position, a firing circuit, means in connection with the selector and controlled by the operating circuit for connecting the firing circuit with the grounded mine circuit when said selector has reached a selective position connected with a grounded mine circuit, a casemate control assembly, a single conductor extending between the casemate control assembly and the distributing assembly at the distant station, said conductor providing a path of electrical distribution for the operating and firing circuits, and means at the casemate assembly for impressing operating power and high potential firing power on said conductor.

10. A submarine mine control system comprising a distant station including a group of submerged mines and a distributing assembly in the midst of the mine group and controlling the distribution of electrical energy thereto, a mine circuit for each mine and a ground connection for each of said mine circuits, an impact mechanism in each mine circuit and operable when a mine has been struck to connect the mine circuit with the ground, an automatic selector having a home position and a series of selective positions, each of which is connected with one of the mine circuits, an operating circuit, means in the operating circuit and coacting with the selector for normally maintaining the latter on its home position, means controlled by said operating circuit and effective when a mine circuit has been grounded to step the selector from its home position and to lock it on the selective position connected with the grounded mine circuit, a firing circuit, means for connecting said firing circuit with the grounded mine circuit when the selector has stopped on the selective position connected with said grounded mine circuit, a casemate control assembly, a single conductor extending between the casemate control assembly and the distributing assembly at the distant station, said conductor being connected at the distant station to the operating and firing circuits, means at the casemate control assembly for impressing operating power and firing power on said interconnecting conductor.

11. A submarine mine control system comprising a distant station including a submerged distributing assembly and a series of mines connected therewith, a mine circuit in connection with each of said mines, the respective mine circuits including a ground, impact operated means in each mine circuit and operable when a mine has been struck to connect the ground with the mine circuit, an automatic selector having a home position and a series of selective positions, each of which is connected with one of the mine circuits, an operating circuit, a firing circuit, means in said operating circuit and coacting with the selector for stepping the selector one step from its home position when a ground has been established on one of said mine circuits, a stepping circuit in connection with the operating circuit, said stepping circuit including means for stepping said selector from the position of its initial step to the selective position whereby to connect the firing circuit with the grounded mine circuit, a casemate control assembly, a single conductor extending between the casemate assembly and the distributing assembly, said conductor being connected to said operating and said firing circuits, means at the casemate control assembly for impressing operating power and firing power upon said interconnecting conductor.

12. A submarine mine control system comprising a distant station including a submerged distributing assembly, a series of submerged mines connected therewith, a mine circuit in connection with each of said mines, the respective mine circuits including a ground, impact operated means in each mine circuit and operable when the mine has been struck to connect the ground with the mine circuit, an operating circuit and a firing circuit, an automatic selector comprising a contact bank including upper,

lower and intermediate rows of mine contacts, the mine contacts in the upper and intermediate rows being connected to the contacts in the lower row, and to the mine circuits, a stepping mechanism in the operating circuit, said mechanism being non-responsive to the current normally flowing through said circuit, but operable by an increase in current flow, produced when a ground has been established on a mine circuit, a pair of interconnected wipers and a metallic disk, said wipers serving the upper

10 and intermediate rows and said disk engaging the lower row of contacts, said wipers and disk being simultaneously responsive to the energization and deenergization of the stepping mechanism whereby when a ground has been formed on one of the mine circuits the wipers and disk will be rotated until one of said wipers engages the contact connected to the grounded mine circuit, means in connection with the operating circuit and operable when one of the wipers has engaged a contact to disrupt the circuit of the stepping mechanism and to lock the wiper 20 on the engaged contact, a casemate control assembly, a single conductor extending between the casemate assembly and the distributing assembly at the distant station, said conductor being connected to said operating and said firing circuits, means at the casemate control assembly 25 for impressing operating and firing power upon said interconnecting conductor, and additional means in connection with the casemate assembly and the distant station assembly to connect the firing circuit with the grounded mine circuit.

13. A submarine mine control system comprising a distant station including a distributing assembly, a series of submerged mines connected therewith, a mine circuit in connection with each of said mines, the respective mine circuits including a ground, an impact operated means in each mine circuit and operable when a mine has been struck to connect the ground with the mine circuit, an operating circuit, a firing circuit, an automatic selector comprising a contact bank including upper, lower and intermediate rows of mine contacts, each of the mine 35 contacts in the upper and intermediate rows being connected to the contacts in the lower row and with one of the mine circuits, a stepping mechanism included in the operating circuit and responsive to an increase in the normal flow of current produced when a ground has been formed on one of the mine circuits, a pair of wipers serving the upper and intermediate rows of contacts and a metallic disk in engagement with the contacts in the lower row of the said contact bank, said wipers and disk being simultaneously responsive to the energization and deenergization of the stepping mechanism, means normally 40 connecting all the mine circuits in parallel with the operating circuit, whereby when a ground has been formed on the mine circuit, the resulting increase in current flow through the operating circuit causes the stepping mechanism to be energized and deenergized to step the selector until one of its wipers engages a contact connected with the grounded mine circuit, means in connection with the operating circuit for stopping the selector when one of its wipers has engaged a ground connected contact, a casemate control assembly, a single conductor extending between the casemate assembly and the distributing assembly, said conductor being connected to said operating and said firing circuit, means at the casemate control assembly for impressing operating and firing power upon said 45 interconnecting conductor, and additional means at the casemate assembly and at the distributing assembly for connecting the connected mine circuit to ground with the firing circuit whereby to fire said mine.

14. A submarine mine control system comprising a distant station including a submerged distributing assembly and a series of submerged mines connected therewith, a mine circuit in connection with each of said mines, the respective mine circuits including a ground, an impact operated means in each mine circuit and operable when a mine has been struck to connect the ground with the

mine circuit, an operating circuit, a firing circuit, an automatic selector comprising a contact bank including upper, lower and intermediate rows of mine contacts, the mine contacts of the upper and intermediate rows of contacts being connected to the contacts in said lower row and to the mine circuits, a home contact in each of said rows of contacts, a pair of interconnected wipers serving the upper and intermediate rows of contacts, a peripherally notched metallic disk in engagement with the lower row of contacts, said wipers and disk being simultaneously rotatable, means in connection with said disk for normally maintaining the wipers of the selector on their home contacts, means in the operating circuit and controlled by the establishment of a ground on one of the mine circuits to step the wipers of said selector and the notch in said disk, from their home contacts to the contact of the grounded mine circuit, means for locking said wipers and disk on the engaged contact, a casemate control assembly, a single conductor extending between the casemate control assembly and the distributing assembly, said conductor being connected to said operating and said firing circuits, and means for connecting the contact engaged wiper with said firing circuit.

15. A submarine mine control system comprising a distant station including a distributing assembly and a series of submerged mines connected therewith, a mine circuit in connection with each of said mines, the respective mine circuits including a ground, an impact operated means in each mine circuit and operable when a mine has been struck to connect the ground with the mine circuit, an operating circuit, a firing circuit, an automatic selector comprising a contact bank including upper, lower and intermediate rows of mine contacts, the said mine contacts of the upper and intermediate rows of contacts being connected to the contacts in said lower row, and the mine circuits, a home contact in each of said rows of contacts, a pair of interconnected wipers serving the upper and intermediate rows of contacts and a peripherally notched metallic disk in engagement with the lower row of contacts, said wipers and disk being simultaneously rotatable, means for normally maintaining the wipers on their home contacts and the notch in said disk overlying its home position, means in the operating circuit and controlled by the establishment of a ground on one of the mine circuits to step the wipers of said selector and the notch in said disk from their home contacts to the contact of the grounded mine circuit, a casemate control assembly, a single conductor extending between the casemate control assembly and the distributing assembly, said conductor being connected to said operating and said firing circuits, and in connection with the selector for connecting the firing circuit with the wiper engaged contact.

16. A submarine mine system comprising a casemate control assembly, a distant station assembly including a series of submerged mines, a single path of electrical distribution between the assemblies, means for selectively firing any of said mines from the casemate control assembly and on impact, said means including an automatic selector in connection with the casemate and with the distant station assemblies respectively, said selectors having a home position and a series of selective positions, signal circuits connected with the selective positions of said casemate selector, signals in said circuits, a source of energy for said signal circuits, a mine circuit connected with each of the positions of the distant station selector, means for stepping the selectors at the casemate and distant station assemblies from their home positions to a selective position in coordinated relation, means in connection with the casemate selector to connect a signal circuit with a source of energy when said selector attains a selective position, an operating circuit, a locking circuit and a firing circuit, means for successively connecting these circuits with each of the mine circuits, and a source

of operating, locking and firing power connected with said operating, locking and firing circuits.

17. A submarine mine system comprising a casemate control assembly, a distant station assembly including a series of submerged mines, a single path of electrical distribution between the assemblies, means for selectively firing any of said mines from the casemate and on impact, said means including a pair of automatic selectors, one being in the casemate assembly, the other in the distant station assembly, means for stepping said selectors in co-ordinated relation, said selectors having a home position and a series of selective positions, a signal circuit connected with each of the selected positions of the casemate selector, a source of energy for the signal circuits, a mine circuit for each of the submerged mines, the respective mine circuits being connected to the selective positions of the distant station selector, means for normally maintaining the selectors on their home positions, means for stepping said selectors to a selected position, means in connection with the casemate selector for connecting a signal circuit with the source of energy when said selector is on a selective position, an operating circuit, a locking circuit and a firing circuit, means for successively connecting said circuits with the respective mine circuits and a source of operating, locking and firing power for said operating, locking and firing circuits.

18. A submarine mine system comprising a casemate control assembly, a distant station assembly including a series of submerged mines, a single path of electrical distribution between the assemblies, means for selectively firing said mines from the casemate and on impact, said means including a pair of automatic selectors, one of said selectors being associated with the casemate assembly, the other with the distant station assembly, said selectors having a home position and a series of selective positions, means for stepping the selectors in coordinated relation, means for normally maintaining the selectors on their home position, and means in connection with the casemate assembly and distant station assembly to stop the selectors on a selective position, and means at the casemate assembly to visually indicate the selective position upon which the selectors have stopped.

19. A submarine mine system comprising a casemate control assembly, a distant station assembly including a series of submerged mines, a single path of electrical distribution between the assemblies, means for selectively firing said mines from the casemate and on impact, said means including a pair of automatic selectors, one of said selectors being associated with the casemate assembly, the other with the distant station assembly, said selectors having a home position and a series of selective positions, means for stepping the selectors in coordinated relation, means for normally maintaining the selectors on their home position, and means in connection with the casemate assembly and distant station assembly to stop the selectors on a selective position, means at the casemate assembly to visually indicate the selective position upon which the respective selectors have stopped and means for restoring the coordinated stepping relation of the selectors when said relation has become disrupted.

20. A submarine mine system comprising a casemate control assembly, a distant station assembly including an impulse relay unit, a synchronizing relay unit and a ground connection at the casemate assembly, a series of submerged mines, a single path of electrical distribution between the assemblies, means for selectively firing said mines from the casemate and on impact, said means including a pair of automatic selectors, one of said selectors being associated with the casemate assembly, the other with the distant station assembly, said selectors having a home position and a series of selective positions, means for stepping the selectors in coordinated relation, means for normally maintaining the selectors on their home position, means in connection with the casemate assembly and distant station assembly to stop the selectors on a selective

position, and means for restoring the coordinated stepping relation of the selectors when said relation has become disrupted.

21. A submarine mine system comprising a casemate control assembly, a distant station assembly including a series of submerged mines, a single path of electrical distribution between the assemblies, means for automatically firing any of said mines on impact, said means including a distant station automatic selector having a home position, and a series of selective positions, means for normally maintaining the selector on its home position, means for stepping said selectors in coordinated relation from their home to a selective position, a source of firing power, a firing switch controlling the application of said firing power, and means in each for preventing the application of firing power to the system after a mine has been fired, until said firing switch has been opened.

22. A submarine mine system comprising a casemate control assembly, a distant station assembly including a series of submerged mines, a single path of electrical distribution between the assemblies, means for automatically firing any of said mines on impact, said means including a distant station automatic selector having a home position, and a series of selective positions, means for normally maintaining the selector on its home position, means for stepping said selectors in coordinated relation from their home to a selective position, a source of firing power, a firing switch having an open and closed position, an electro-magnetic means in connection with the casemate assembly and coacting with the firing switch to preclude the application of firing power to the electrical path between the assemblies, until said firing switch has been restored to its open position.

23. A submarine mine system comprising a casemate control assembly, a distant station assembly including a series of submerged mines, a single path of electrical distribution between the assemblies and means for selectively firing any of said mines from the casemate and on impact, said means including a pair of automatic selectors in connection with the casemate and distant station assemblies respectively, said selectors having a home and a series of selective positions, means for stepping said selectors in coordinated relation from their home position to a selected position, means for returning said selectors to and retaining them on their position, said means including a peripherally notched metallic disk in connection with the distant station selector.

24. A submarine mine system comprising a casemate control assembly, a distant station assembly including a series of submerged mines, a single path of electrical distribution between the assemblies, and means for selectively firing any of the mines of said series from the casemate and on impact, said means including a distant station automatic selector having a series of selective positions and a home position, means in connection with the selector for normally maintaining the latter on its home position, and additional means controlled by mine impact for stepping the selector to and locking it on one of its selective positions, said additional means including an automatic casemate selector and a plurality of mine signals corresponding in number to the number of mines at the distant station and indicating at the casemate the position of the distant station selector with respect to its selective position.

25. A submarine mine system comprising a casemate control assembly, a distant station assembly including a series of submerged mines, a single path of electrical distribution between said assemblies, and means for selectively firing any of said mines from the casemate and on impact, said means including a distant station automatic selector having a series of selective positions and a home position, means for normally maintaining the selector on its home position and additional means controlled by

mine impact for stepping the selector to one of its selective positions, said additional means including an automatic selector at the casemate assembly, means in connection with said assembly for stepping said casemate selector in coordinated relation with the distant station selector and a series of mine signals corresponding in number to the number of mines at the distant station and controlled by the casemate selector to indicate the position of the distant station selector with respect to its selected position.

26. A submarine mine system comprising a casemate control assembly, a distant station including a series of submerged mines, a single path of electrical distribution between the assemblies, means for selectively firing any of the mines of said series on impact, said means including a distant station automatic selector having a series of selective positions and a home position, a casemate selector having a series of selected positions and a home position, means for normally maintaining the selectors on their home positions and additional means controlled by mine impact and from the casemate for stepping the selectors to and locking them on a selective position, means in connection with the casemate and distant station assemblies for causing their selectors to step in coordinated relation, a plurality of mine signals at the casemate controlled by the selective positions of said casemate selector to indicate the position of the distant station selector with respect to its selected position, means in connection with the casemate and distant station selectors for recoordinating their stepping movement, means associated with the casemate selector for visually rechecking the mines at the distant station in their reverse order.

27. A submarine mine system comprising a casemate control assembly, a supervisory assembly, means electrically interconnecting the supervisory assembly with the control assembly, a distant station assembly including a series of submerged mines, a single path of electrical distribution between the casemate control assembly and the distant station assembly, and means in connection with the respective assemblies for automatically firing any of said mines on impact, said means including a distant station selector, a casemate selector, said selectors having a series of selective positions and a home position and means electrically related with said assemblies for stepping said selectors in recoordinated relation from their home positions to a selective position, means for normally maintaining the casemate and distant station selectors on their home positions and signal means in the supervising assembly for indicating the position of the distant station selector with respect to its home and selective positions.

28. A submarine mine system comprising a casemate control assembly, a distant station assembly including a series of submerged mines, a single path of electrical distribution between the assemblies, and means for selectively firing any mine which has been sufficiently tilted by impact, said means including a distant station automatic selector having a series of selective positions and home positions, means for normally maintaining the selector on its home positions, means controlled by mine impact for stepping the selector to and locking it on one of its home positions, and additional means in the casemate assembly and coacting with the distant station selector to release said selector from the selective position upon which it has locked and to cause said selector to return to its home positions.
